UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC COMPANY, A CORPORATION OF ILLINOIS.

SEMI-AUTOMATIC TELEPHONE SYSTEM.

1,323,483.

Specification of Letters Patent.

Patented Dec. 2, 1919.

Application filed May 14, 1906, Serial No. 316,742. Renewed February 8, 1909. Serial No. 275,854.

To all whom it may concern:

Be it known that I, TALBOT G. MARTIN, a citizen of the United States of America, and resident of Chicago, Cook county, Illinois, have invented a certain new and useful Improvement in Semi-Automatic Telephone Systems, of which the following is a specification.

My invention relates to telephone systems in general, but more particularly to telephone systems of that particular character known as semi-automatic systems—that is to say, telephone systems in which both manual switchboards and automatic switches are employed for establishing connection between calling and called subscribers' lines.

Generally stated the object of my invention is the provision of an improved and highly efficient telephone exchange system.

Special objects of my invention are the provision of an improved and highly efficient semi-automatic telephone exchange system; the provision of improved means for supervising the system both with respect to service between subscribers' lines and certain kinds of trouble, as will hereinafter more fully appear; the provision in a system of this character of improved release-circuits for releasing or restoring whatever automatic switching means may have been found necessary in establishing connection between any two subscribers' lines; the provision of an improved arrangement for dividing the exchange into a main or central station and a plurality of outlying auxiliary or sub-central stations, whereby greater economy and efficiency are obtained; the provision of an improved arrangement by which each subscriber's line entering a sub-central station is provided with an improved individual-switch for making connection with an idle trunk-line leading from such sub-central station to the main or central station; the provision of an improved arrangement whereby the capacity of a telephone system may be increased to any desired extent at a comparatively small cost and expenditure of time and labor; the provision of an improved arrangement for effecting a reduction in the equipment necessary for the manual board operators; the provision of an improved arrangement involving operators' cord-circuits adapted to operate in conjunction with individual

switches and in connection with improved repeaters, as will hereinafter more fully appear; and the provision of certain combinations, details and features of improvement tending to increase the general efficiency and serviceability of a telephone exchange system of this particular character.

In a system characterized by my invention a subscriber whose line terminates at a sub-central station can make a call in the usual manner—that is, in the manner ordinarily employed in manual exchanges. As soon as he takes down his receiver the so-called individual-switch in which his line terminates automatically selects for him an idle trunk-line leading from the sub-central station to the main or central station. At this main or central station the trunk-line thus automatically selected for the calling subscriber terminates in the manual board, and is there provided with a visual line signal. The operator at this board, observing the line signal, picks up the answering-plug of the cord-circuit corresponding to this trunk-line and inserts the same in the jack connected therewith. She can then press her listening-key in the ordinary manner and by means of her talking set converse with the calling subscriber and receive his order for the connection. If the calling subscriber desires connection with the line of a subscriber terminating in the same or some other sub-central station, the operator then employs her calling device or impulse-transmitter for operating a connector at the sub-central station at which the called line terminates. She thus operates the said connector and causes the same to make connection directly with the line of the called subscriber. After this, the connector can automatically ring or signal the called subscriber in the ordinary and well-known manner. If, however, the calling subscriber desires connection with a subscriber's line which terminates directly at the main or central station, the operator will then simply connect the calling plug of the cord-circuit with a multiple-jack which is connected with the called line and which is located on her board. She then rings or calls the called subscriber. In the other case, namely when the called subscriber's line terminated at the sub-central station, the operator inserted the calling plug of the cord-circuit in the jack of a trunk-line leading to such

sub-central station. In either case, however, the calling subscriber obtains connection with the operator through the medium of his individual-switch, and from this point on the operation is either purely manual or semi-automatic, according to whether the called subscriber's line terminates in a multiple-jack on the operator's board, or in the multiple-contacts of connectors located 10 at a sub-central station. In one case, also, the ringing or signaling of the called subscriber is done by the operator at the manual board; but in the other case the ringing is done by the automatic ringing connector. 15 With this arrangement the operator requires but little equipment in order to take care of a large number of subscribers.

To the foregoing and other useful ends, my invention consists in matters hereinafter 20 described and claimed.

In the accompanying drawings,

Figure 1 is a diagram illustrating how my improved system is used in connection with a purely manual exchange; and the 25 said manual exchange is shown to the left, and the trunking positions allotted to out-lying sub-centrals and their allotted sub- stations employing individual-switches are indicated to the right; and the said sub- 30 centrals are represented by circles.

Figs. 2, 3 and 4 are diagrammatic views that represent an established connection between calling and called subscribers whose lines terminate at a sub-central station; and 35 the substations are designated as #2050 and #2120, respectively, and the intermediate apparatus for maintaining the said connection consists of an individual-switch A, a battery B for operating said switch and 40 all other switches, a repeater C, a cord- circuit D with allotted line and multiple jacks, a connector E at the called sub- central, and the individual-switch A¹ of the called line; and for selectively oper- 45 ating the individual-switches each sub- central or group of individual-switches is provided with a master-switch F which, in Fig. 2, is shown with the calling substation #2050, the individual-switch A and the repeater C.

Fig. 3 is a diagram showing the cord- circuit allotted to one of the trunking operators' position at the central or main station.

Fig. 4 is a diagram showing the connector- switch E and the individual-switch A¹ of the called line, together with the called telephone.

Fig. 5 is also a diagrammatic view of the 60 individual-switch A and of the master- switch F, with circuits appertaining thereto.

Fig. 6 is a diagrammatic perspective view of the connector-switch of the general class described in Patent No. 815,176, issued 65 March 13, 1906, to Keith, Erickson and

Erickson showing the automatic ringing arrangement described in application Serial No. 312,156, filed April 17, 1906, issued as Patent No. 1,194,339, Aug. 8, 1916.

It will be observed that the battery B 70 appears in various figures, but it will be understood that said battery is located at the main-central office with, preferably, its positive terminal grounded at G. From the non-grounded terminal of said battery leads 75 are distributed to the different sub-centrals and to various parts of the system wherever it may be necessary. This arrangement, however, is not essential since, if desired, sub-batteries may be provided at any de- 80 sired point.

The individual-switches are of the type described in application Serial No. 258,026, filed April 29, 1905. Each individual- switch comprises a release-magnet 2, a trip- magnet 3, a bridge-cut-off-relay 4, and a bank H with ten jack positions, each position comprising three individual springs 5, 6 and 7 and five multiplied springs 8, 9, 10, 11 and 12—that is, springs that are 90 multiplied in the same bank and to similar springs of all other banks. Each of said bank jacks corresponds to a trunk-line, any one of which trunk-lines may be seized by the individual-switch A. Each of said trunk- lines comprises two line-conductors and a trunk-release conductor, and in Fig. 5 the trunk-line allotted to the jack there shown terminates in the springs 5 and 6, and the corresponding release-trunk-conductor in 100 the spring 7. It has been described that the said jack, shown in Fig. 5, represents the first jack of the bank H. Like this jack there are corresponding jacks in every other bank of the same group. Furthermore, in 105 all of said corresponding jacks all similar springs 5 are connected in multiple. The same is true of all similar springs 6 and all similar springs 7. Of the said bank H only one of the jack positions is shown. Adapted 110 to engage the said bank jacks one at a time there is provided a plunger 13 which is pivotally secured to a plunger-arm 14, said plunger-arm being held in position by a pin 15 that rises from the base of the individual-switch, which base is not shown. The release-magnet 2 controls an armature 16 that is held in normal position by any suitable spring 17 and that carries on its forward end the armature 18 of the trip- magnet 3, the said armature 16 being pivoted to the base of the individual-switch by the pin 19. Upon the end of the trip- magnet armature 18 there is a hook-like 120 projection 20 that normally locks in engagement with the abutment 21 and thereby retains the plunger 13 in normal engagement with a receiving channel 22 that extends longitudinally of a shaft 23 that is common to all individual-switches of the 125 130

same group. Said shaft is out of the control of the individual-switch, but is operated altogether by the master-switch F. The said master-switch is provided with the 5 bank I and auxiliary-relay 24 and differential-relay 25 and a motor-magnet 26. The bank I is composed of a number of contacts 27 (one for each trunk-line leading from the individual-switch bank H) and a member 28 common to said contacts. Adapted 10 to engage said bank there is a wiper 29 by means of which any one of the said contacts 27 may be placed in electric connection with the common plate 28. The wiper 29 is a 15 part of a wiper-arm formed by the said wiper and a cam 30. The said cam normally rests in engagement with either one of four pins 31, 32, 33 or 34 carried on a ratchet-wheel 35. Said ratchet-wheel normally 20 rotates in the direction of the arrow and is checked against backward rotation by a pawl 36. The cam 30 is retained in engagement with the pins upon said ratchet-wheel 35 by a suitable spring 37 whereby 25 the wiper-arm is given a perpetual tendency to rotate the ratchet-wheel 35 in a clockwise direction. The mechanism for rotating the said ratchet-wheel 35 and, therefore, for shifting the wiper 29 from one position 30 to another comprises a pawl 38 upon the end of the armature 39 of the motor-magnet 26, whereby whenever the said magnet 26 is energized the ratchet-wheel 35 is rotated one step. The wiper 29 and cam 30 are 35 so adjusted that when the pin 31 engages the said cam 30 at a point marked by the line 40 the wiper 29 engages the contact-point 41; when said pin advances by the line marked 42 the wiper 29 passes the contact-point 43; and when the said pin passes to the end of the cam 30 the wiper 29 reaches the contact 44. Having reached the contact 44, if the ratchet-wheel 35 is advanced another step, the cam 30 disengages from said 45 pin 31 and meets the pin 32 at the point 40 and so on. The construction is such that whenever a guarding potential appears at the contact-point of the bank I engaged by the wiper 29 the differential-relay 25 is energized, which latter upon attracting its armature 45 presses the springs 46 and 47 into contact and thereby establishes an energizing circuit through the motor-magnet 26, whereby the ratchet-wheel 35 is advanced 50 one step. The common shaft 23, previously mentioned, is attached to the cam-arm at the point 48, and it will be evident each time the said cam-arm is operated that the shaft 23 will be rotated correspondingly, carrying with it all idle plungers normally resting in the channel 22. To illustrate: If the wiper 29 is resting upon the contact 41 when the individual-switch A is operated, the plunger-shaft is then in a position to direct 55 the plunger 13 into the first jack of the bank

H, shown in Fig. 5. A guarding potential is then established at the said contact-point 41, which causes the differential-relay 25 to be energized. Said relay then causes the motor-magnet 26 to be operated so that 70 the wiper 29 and plunger-shaft 23 are advanced to the next position in which the wiper 29 engages the contact-point 43. If the contact 43 is also provided with a guarding potential—that is, if the second jack of 75 the bank H is busy—the differential-relay 25 is still maintained energized so that the motor-magnet 26 may operate once more to carry the wiper 29 and shaft 23 to the next position. A step-by-step actuation of the 80 shaft 23 and wiper 29 takes place until the shaft 23 carries all idle plungers to a point opposite the bank jacks that are not occupied.

The substation may be of the ordinary 85 common battery type in which the subscriber's line-circuit is normally closed through a ringer 49 and the condenser 50 when the switch-hook 51 is down. The receiver 52 is in series with the secondary 90 winding 53 of the induction-coil 54, and when the switch-hook is up the primary winding 55 of the said induction-coil, in series with the transmitter 56, is bridged across the line instead of the ringer 49. 95

The repeater C is very simple and comprises a couple of condensers 57 and 58 located respectively on the vertical and rotary sides of the main circuit. On the front side of said condensers the vertical-line-relay 59 is bridged between the vertical side of the line and the non-grounded terminal of the battery, while the rotary-line-relay 60 is bridged between the rotary side of the line and the ground. Said vertical and 100 rotary line-relays, respectively, control circuits to be described. Upon the back side of the said condensers the vertical-back-bridge-relay 61 is normally connected between ground and the vertical side of the line 105 through a couple of springs controlled by the rotary-line-relay 60. A signal-relay 62 is normally connected between ground and the trunk-release-conductor that leads to the individual switch banks. Said relays 61 110 and 62 also control circuits that will be described. 115

The cord-circuit, in addition to having the usual front supervisory relays 63 and 64 and back supervisory relays 65 and 66, is 120 provided with a calling device having a couple of line-springs 67 and 68 and a ground-spring 69, whereby the operator by plugging in the proper trunk-line may operate automatic switches for establishing 125 connection between the calling and called subscribers. The line-cut-off-relay 70 and the line-relay 71 are of the usual type. The outgoing trunks terminate in multiple jacks of which there is one to each trunking op- 130

erator. Of the said jacks, in Fig. 3, two are shown, namely 72 and 73. Said jacks are each provided with a signal-lamp so that if any one of the trunking operators is 5 using a particular trunk the signal-lamp to each trunking operator's position will remain lighted as long as the said trunk is used by any one of the operators. Alotted to each trunk-line there are a quick-acting 10 relay 74 and a slow-acting relay 75 for releasing the automatic switches. Between the trunking operators and the local operators a system of order-wires is provided whereby the local operators may deliver an 15 order to any one of the trunking operators whenever the local subscribers wish to connect with the sub-central subscribers. One of the local operator's signal-buttons is shown at J while the order signal-lamp 76 20 is shown in connection with the cord-circuit D.

It will be evident that the individual-switch A¹ is like the individual-switch A and will, therefore, need no further description. Beneath the said individual-switch 25 A¹ a differential-relay 77 is shown that corresponds to the differential-relay 25 of the master-switch F.

In the establishment of a connection between two subscribers the following apparatus and circuits are involved. If the subscriber #2050 (Fig. 2) desires to establish 30 connection with the subscriber #2120 he removes his receiver 52 from the switch-hook 51, thereby closing a circuit between the line-conductors 78 and 79 through the transmitter 56 and primary winding 55 of the induction-coil 54. Normally the vertical-line-conductor 78 is connected to ground G¹ 35 while the trip-magnet 3 is normally connected between the rotary-line-conductor 79 and the non-grounded terminal of battery B. Therefore, the establishment of connection 40 between the said conductors 78 and 79, as described, causes the trip-magnet 3 to be energized by a flow of current from ground G¹ through the transmitter 56 to the rotary-line-conductor 79, and thence through the trip-magnet 3, conductor 85, springs 84 and 45 50 55 60 65 70 75 80 85 90 95 100 105 110 115 120 125 130

83 to the battery-lead 80 and through battery B to ground G. The trip-magnet 3 will then attract its armature 18 and thereby disengage the terminal 20 from the abutment 21, at which time a spring 81 forces the plunger 13 into the bank jack, as shown in Fig. 5. The plunger 13 being thus operated forces the springs 7, 10, 11 and 12, respectively, into contact with the springs 9, 8, 5 and 6. A number of circuits are simultaneously set up upon the operation of the plunger 13 and a number of relays and magnets are energized as follows: When the springs 8 and 10 come into contact they establish a guarding potential by way of the private-normal-conductor 82 at the connector-banks that are allotted to the group of subscribers of the twentieth hundred, so that no calling subscriber may be able to connect with the calling line #2050 by way of the conductors 82^a and 82^b after the plunger 13 has once been tripped. The closure of contact between the springs 9 and 7 sets up a circuit between the non-grounded terminal of battery B and contact 41 of the master-switch I as follows: from the battery B through the battery-lead 80 and release-magnet 2 to the said springs 9 and 7 and conductor 86 to the contact-point 41. The establishment of said guarding potential at that point energizes the differential-relay 25, which latter then causes the motor-magnet 26 to operate to carry the wiper 29 and the shaft 23 to the next non-guarded position, as previously described. Also, the closure of contact between the springs 12 85 and 6 extends the subscriber's vertical-line-conductor 78 to the repeater C, and since the said conductor is grounded at G¹ through the springs 87 and 88 the vertical-line-relay 59 is also energized. This latter 90 relay then causes the springs 89 and 90 to be forced apart to destroy a circuit between the said spring 90 and the spring 91 controlled by the vertical-back-bridge-relay 61. Also, when the springs 5 and 11 close in 95 contact, a circuit is then established through the rotary-line-relay 60 from ground G¹ by way of the transmitter 56 and winding 55 of the induction-coil 54, thence over the rotary-line-conductor 79 through the said 100 springs 11 and 5 to the said rotary-line-relay 60, thence to ground G². Therefore, the said rotary-line-relay 60 is short-circuited between the ground terminals G¹ and G². When the aforesaid springs 10 and 8 come 105 into contact not only is there a guarding potential established at the connector banks by way of the private-normal-conductor 82, but an energizing circuit is established through the cut-off-magnet 4 from ground 110 G² through the said springs 8 and 10, conductor 92, cut-off-relay 4 to the battery-lead 80 and through battery B to ground G. The aforesaid relay 4, upon becoming energized, forces the springs 88 and 93 away from the 115 springs 87 and 94, thereby breaking the circuit between ground G¹ and the vertical-line-conductor 78, and between the trip-magnet 3 and the spring 93. At the instant that the springs 87 and 88 are pressed apart by the relay 4 the connection to ground for maintaining the vertical-line-relay 59 energized is furnished by the ground G² through the rotary-line-relay 60 and through the substation transmitter 56 to the vertical-line-conductor 78. At once the said rotary-line-relay 60 pulls up so that the said vertical and rotary line-relays 59 and 60 are energized in series, the current in which circuit passes from the said ground G² through 120 125 130

the primary winding 55 at the substation, transmitter 56, vertical-line-relay 59 to the battery-lead 80 and through battery B to the ground terminal G. When the springs 5 9 and 7 close contact, as described, not only is there a guarding potential established at the contact 41, but an energizing circuit is set up through the signal-relay 62 from ground G⁴ through the said relay and 10 through the springs 7 and 9, release-magnet 2 to the battery-lead 80, thence through battery B to ground G. Said signal-relay 62 is wound to a very high resistance, about four thousand ohms, more or less. Said relay 15 remains energized from the time that the individual-switch A operates until the subscriber releases the switching apparatus, in a manner to be described. Normally the said relay plays no part in the establishment 20 of connections, as it is nothing more than a trouble supervisory relay for transmitting signals to the operator at the main exchange, in a manner to be described. The vertical and rotary line-relays 59 and 60, however, 25 are only wound to about three hundred and fifty ohms each, and the vertical - back-bridge-relay 61 to about five hundred ohms. After the subscriber has established connection with the repeater C, and upon energizing the rotary-line-relay 60, as described, 30 the springs 95 and 96 are separated, and the springs 97 and 98 are also separated, but the springs 95 and 97 are brought into contact. As a result the vertical - back-bridge-relay 61 is bridged across the incoming 35 trunk-conductors 99 and 100, whereby the said relay is connected in series with the line-signal-relay 71, and whereby both of said relays are energized. The magnetizing 40 current flows from ground G⁵ through the contact 101, armature 102 of the line-cut-off-relay 70, vertical-trunk-conductor 99, vertical-back-bridge-relay 61, springs 95 and 45 97 of the rotary-line-relay 60 to the rotary-trunk-conductor 100, thence through the 50 armature 103 of the line-cut-off-relay 70, contact-point 104, line-relay 71 to the battery-lead 80, and through battery B to the ground terminal G. The vertical - back-bridge-relay 61 of the repeater C upon 55 attracting its armature forces the springs 91 and 105 into contact, whereby the said spring 91 and, therefore, the spring 89 of the vertical-line-relay 59 is connected with ground G⁶ for future use. Not only are the springs 91 and 105 in contact, but since the signal-relay 62 is energized the spring 106 is also in contact with spring 105; and since the rotary-line-relay 60 is energized the 60 connection between said springs 105 and 106 has no consequence at this time. The line-relay 71, at the central station, upon energizing draws the armature 107 onto the contact-point 108, whereby the line signal-lamp 109 is bridged between ground G⁷ and the 65 battery-lead 80. The said lamp, upon being thus connected, is lighted and gives a signal to the trunking operator, indicating that some one is calling. Said operator then inserts the answering end of the cord-circuit 70 D into the jack 110 and energizes the line-cut-off-relay 70 by establishing a circuit through said relay from ground G⁸ through the said relay 70, jack sleeve 111, sleeve supervisory relay 64 to the battery-lead 80 75 and through the battery B to ground G. Both of said relays 70 and 64 become energized so that the armatures 102 and 103 of the line-cut-off-relay 70 are attracted by the said relay and the vertical-trunk-conductor 80 99 and the rotary-trunk-conductor 100 are placed in connection, respectively, with the tip-spring 112 and the sleeve 111, as shown. As a result the previously described energizing circuit for the vertical-back-bridge-relay 61 is transferred from ground G⁵ at the line-cut-off-relay 70 to the ground terminal G and through the tip supervisory relay 63, whereby not only the said relay 61 is retained energized, but the relay 63 is also energized. The transfer or change of circuit occurs so quickly that the relay 61 has no time to deenergize. The current in this last circuit, it will be seen, passes from ground G through the relay 63, tip-spring 112, vertical-trunk-conductor 99, relay 61, rotary-trunk-conductor 100 to the sleeve 111, thence 95 through the supervisory relay 64 to the battery-lead 80 and through the battery B to ground G. When the armature 103 leaves 100 the contact-point 104, at the time when the line-cut-off-relay 70 is energized, the line-signal-relay 71 deenergizes and releases the armature 107, whereby the line-signal-lamp 109 is extinguished. As soon as the sleeve 105 supervisory relay 64 attracts its armature 113 the energizing circuit is closed through the back supervisory lamp 114 from ground G through the armature 115 of the tip back supervisory relay 65, thence through the contact-point 116, armature 117 of the sleeve back supervisory relay 66, through the contact-point 118, lamp 114, contact-point 119, and armature 113 to the battery-lead 80 and through battery B to ground G. It will be 110 noticed that for the purpose of preventing the front supervisory lamp 120 from lighting up when the operator inserts her plug in the jack 110 the armature 121 of the relay 63 is attracted and thereby separated from 115 the contact-point 122. Having plugged into the calling line the operator presses the key a and thereby throws her talking set across the conductors 123 and 124 to communicate with the calling subscriber. When the 120 springs 125 and 126 engage the contact-points 127 and 128, respectively, the receiver 129 in series with the secondary winding 130 of the induction-coil 131 is bridged across the said line through the condenser 130

132. The transmitter 56 of the substation #2050 being provided with talking battery that flows through the said transmitter in series with the line-relay 59 and 60 of the 5 repeater C, the subscriber, by talking into said transmitter, will cause the resistance of said circuit to be varied. By varying the resistance of the circuit comprising said transmitter, in the usual and well-known 10 manner, the impressed potential between the condensers 57 and 58 is caused to vary in accordance with the vibrations of the transmitter 56, so that talking currents are sent from the condenser 57, thence over the 15 trunk-conductor 99 to the tip-spring 112, thence through the condenser 133, conductor 123, spring 125, contact-point 127, secondary winding 130 of the induction-coil 131, receiver 129, condenser 132, contact-point 20 128, spring 126, conductor 124, condenser 134, sleeve 111 to the rotary-trunk-conductor 100, thence to the condenser 58. The transmitter 135 of the operator's talking set being bridged across the battery B through the 25 impedance-coil 136 is also provided with talking battery current. Said transmitter, like the transmitter 56, will vary the potential between points on either side of said transmitter and thereby cause voice-currents 30 likewise to be sent through the primary winding 137 of the induction-coil 131 and through the condenser 135^a. In a well-known manner said currents affect the secondary winding 130 of the said induction-coil 131, which pass to the substation #2050 through the transmitter 56 and primary winding 55 of the induction-coil 54. The secondary winding 53 of the said induction-coil is thus affected, whereby the voice-waves 35 are reproduced in the receiver 52. The subscriber being asked the number desired will call for the number 2120 and the operator will release the key a. She then inserts the calling terminal of her cord into one of the 40 jacks of the outgoing trunk-lines. The jack 72 being one of such jacks, then as soon as the plug is driven home the quick-acting relay 74 is magnetized as soon as the springs 138 and 139 are pressed into contact, and 45 also the tell-tale lamp 140 is at the same time lighted, as well as all other tell-tale lamps 141 connected in multiple across the conductors 142 and 143, for notifying all trunk operators that have multiples to the outgoing 50 trunk-conductors 144 and 145. The energizing current for the quick-acting relay 74 passes from ground G^a through the springs 138 and 139 and through the said relay 74 to the battery-lead 80 and through the battery B to ground G. In like manner the current that lights the tell-tale lamps flows 55 from ground G^a to the conductor 143, thence through all of said lamps to the conductor 142, and to the battery-lead 80, thence 60 through battery B to ground G. As soon as 65 the relay 74 is energized the armatures 146, 147 and 148 are attracted and when the said armature 147 engages the contact 149 the slow-acting relay 75 is in turn energized. The current for this last relay flows from ground G¹⁰ to the said relay 75, thence through the contact-point 149, armature 147 to the battery-lead 80 and through the battery B to ground G. Said relay, upon energizing, attracts its armatures 150 and 151 70 and establishes a ground connection to the contact-points 152 and 153 for future use. The operator will, of course, know that the trunk-line-conductors 144 and 145 that she has selected lead to the twenty-one hundred 75 sub-central and will proceed to operate the connector-switch at said sub-central to connect with the subscriber 20 in the said twenty-first hundred. She then proceeds by pressing the key b, whereby the springs 154 and 155 80 are withdrawn from the contact-points 156 and 157, respectively, and pressed into contact with the points 158 and 159^a, thereby placing the said spring 154 and 155 in direct connection with the springs 67 and 68 of the calling device. The operator then 85 presses the vertical-button 159 twice and thereby grounds the vertical-trunk-conductor 144 twice. As a result the well-known vertical-line-relay 160 of the connector is 90 energized. Current through said relay flows from ground G¹¹ through the springs 69 and 67, contact-point 158, spring 154, contact-point 161, spring 162, tip-spring 163 to the vertical-trunk-conductor 144, thence through 95 the vertical-line-relay 160 and winding 164 of the differential-relay 165 to the battery-lead 80, thence through battery B to ground G. Both the vertical-line-relay 160 and differential-relay 165 are energized, but the energization of the latter has no significance at 100 present. The vertical-line-relay by pressing the spring 166 and 167 into contact in turn energizes the vertical-magnet 168. The current through this last magnet flows from ground G¹² through the springs 167 and 166 105 and through the private-magnet-springs 169 and 170 to the side-switch-wiper 171, thence through the contact-point 172, vertical-magnet 168 to the battery-lead 80 and through battery B to ground G. The said vertical-magnet being energized twice through the medium of the vertical-armature 173 raises 110 the shaft 174 two steps and the switch-shaft-wipers 175, 176 and 177 are raised to the second level of their respective banks 178 and 179. Having raised the connector-shaft 174 two steps the operator presses the rotary-button 180 once and thereby grounds the rotary-trunk-conductor 145 once. As a result the rotary-line-relay 181 of the connector is 115 energized. The current for energizing said relay flows from ground G¹¹ through the springs 69 and 68, through the contact-point 159^a, thence through the spring 155, 120 125 and to the side-switch-wiper 171, thence through the contact-point 172, vertical-magnet 168 to the battery-lead 80 and through battery B to ground G. The said vertical-magnet being energized twice through the medium of the vertical-armature 173 raises the shaft 174 two steps and the switch-shaft-wipers 175, 176 and 177 are raised to the second level of their respective banks 178 and 179. Having raised the connector-shaft 174 two steps the operator presses the rotary-button 180 once and thereby grounds the rotary-trunk-conductor 145 once. As a result the rotary-line-relay 181 of the connector is energized. The current for energizing said relay flows from ground G¹¹ through the springs 69 and 68, through the contact-point 159^a, thence through the spring 155, 130

contact-point 182, spring 183, sleeve 184 to the rotary-trunk-conductor 145, thence through the said rotary-line-relay 181, winding 185 of the differential-relay 165, vertical-back-bridge-relay springs 186 and 187 to the battery-lead 80, through battery B to ground G. The rotary-line-relay 181 presses the springs 187 and 188 into contact and thereby energizes the private-magnet 188. The current through said private-magnet flows from ground G¹² through the springs 187 and 188, and through the said private-magnet 188 and vertical-back-bridge-relay springs 186 and 187 to the battery-lead 80 and through the battery B to ground G. The private-magnet, upon being energized and deenergized, permits the side-switch retracting spring 189 to draw the side-switch to second position and thereby shift the side-switch-wiper 171 onto the contact-point 190. The operator then again presses the vertical-button 159 ten times corresponding to the digit 0, thereby energizing the vertical-line-relay 160 ten times in the same manner previously described. As a result, since the side-switch-wiper 171 and contact-point 190 are in engagement, each time the springs 166 and 167 come into contact the rotary-magnet 191 is energized. The said relay 160 being operated ten times the rotary-magnet is energized ten times and the switch-shaft 174, through the medium of the rotary-armature 192, is rotated ten steps. The energizing current for the said rotary-magnet 191 flows from ground G¹² and through the private-springs 169 and 170 to the side-switch-wiper 171, thence through the contact-point 190 and through the rotary-magnet 191 to the battery-lead 80 and through the battery B to ground G. The switch-shaft-wipers 175, 176 and 177 are, therefore, carried into engagement with the tenth contact of the second level of their respective banks, from which contacts the normal-conductors 193, 194 and 195 lead to the individual-switch A¹ of the called line, and from thence the normal-line-conductors 193 and 194 extend to the subscriber's station #2120. The operator then for the last time presses the rotary-button 180 once and thereby energizes the rotary-line-relay 181 once, as before, and the private-magnet 188 once, which latter permits the side-switch to pass to third position, thus permitting the side-switch-wipers 196 and 197 to engage the contact-points 198 and 199, respectively. The said wipers 196 and 197 being thus shifted the trunk-conductors 144 and 145 are placed in connection with the normal-conductors 193 and 194, respectively, through the condensers 200 and 201, as shown. It will be noticed that each time that the rotary-line-relay 181 is energized the current passes through the winding 185 of the differential-relay 165, energizing said relay also. But heretofore the energization of said differential-relay has been of no importance. At the same time that the side-switch-wipers 196 and 197 engage the contact-points 198 and 199 the side-switch-wiper 202 finds the grounded contact-point 203 and establishes an energizing circuit through the ringer-relay 204, whereby ringing current from the ringer-generator 205 may be sent over the called subscriber's line 70 for ringing said subscriber's bell. The ringing, as described in my said prior application, occurs intermittently, since the ringer-relay 204 is energized intermittently by means of a circuit-breaker 206 that may be located upon the armature of the ringer-generator 205, but which may, in any desired manner, be kept in perpetual rotation. The said circuit-breaker, as shown, is built like a commutator with alternate conducting and non-conducting sections, but which construction is not absolutely essential. Diametrically opposite conducting segments of said circuit are connected together and the wipers 207 and 208 are so adjusted 85 that when one of the metallic segments on one side is in contact with one of the said wipers, the corresponding segment on the opposite side is in engagement with the other wiper. Each time that the conditions 90 recited occur an energizing current flows through the ringer-relay 204, the path of which current may be traced from ground G¹³ to the contact-point 203, thence through the side-switch-wiper 202, conductor 209, 100 rotary-back-bridge-relay springs 210 and 211, vertical-back-bridge-relay springs 212 and 213, conductor 214, ringer relay 204 and through the circuit-interrupter 206 to the battery-lead 80 and through battery B to 105 ground G. Each time that the said ringer-relay is energized the ringer-relay-springs 215 and 216 are withdrawn from the springs 217 and 218, respectively, and carried into engagement with the springs 219 and 220, 110 whereby the called line is disconnected from the calling line and a circuit established from the ringer-generator 205 through the ringer or bell of the called substation. The path may be traced from the said generator 115 through the ringer-relay-springs 220 and 216, side-switch-wiper 196, contact-point 198, vertical-line-wiper 175 and vertical-normal-conductor 193 to the vertical-line-conductor 221, thence through the condenser 222, ringer 223 to the rotary line-conductor 224, rotary-normal-conductor 194, rotary-line-wiper 176, contact-point 199, side-switch-wiper 197 and ringer-relay-springs 215 and 219 to the ringer-generator 205. In 120 this way the called subscriber's bell continues to ring at intervals until the said subscriber answers, or until the calling subscriber hangs up his receiver. To prevent any other subscriber from calling upon the called line 125 130

while the connection described is maintained, the side-switch-wiper 202 is connected with the private-wiper 177, whereby a guarding potential from ground G^{13} is established at the tenth contact of the second level of the private-bank 179. Said guarding potential provides current at the same time to the cut-off-relay 231 of the individual-switch A^1 (Fig. 4), whereby the 10 said relay is energized. The current passes from ground G^{13} to the private-wiper 177, thence over the private-normal-conductor 195, through the said relay 231 to the battery-lead 80 and through battery B to 15 ground G. For well-known reasons it is desirable to operate the said relay 231 to destroy the connection between the vertical-normal-conductor 193 and the ground G^{14} by separating the springs 232 and 233, and 20 to separate the springs 234 and 235, whereby the trip-magnet 236 is disconnected from the rotary-normal-conductor 194. If, however, the called line should be busy at the instant that the operator presses the rotary- 25 button 180 for the last time to ground the rotary-trunk-conductor 145, as described, the connector operates quite differently. If the said line is busy, as stated, it is well-known that a guarding potential will appear 30 at the tenth private-contact of the second level of the private-bank 179, which contact, of course, is allotted to the called line. That being the case when the rotary-line-relay 181 of the connector is energized 35 for the last time by the operator, as stated, and, of course, while the side-switch is in second position an energizing circuit for the rotary-back-bridge-relay 225, which is normally open between the private-springs 40 170 and 226 at the instant of grounding the rotary line is closed. The said rotary-line-relay 181, upon being energized, causes the private-magnet 188 to be energized and close the said springs 170 and 226 in contact in the well-known and usual manner. 45 As a result, of course, the said rotary-back-bridge-relay 225 is energized by a flow of current from the ground terminal G of battery B to the tenth contact of the second 50 level of the private-bank 179, over circuits for providing said guarding potential at the private-wiper 177, thence by conductor 227 and rotary-back-bridge-relay springs 210 and 211 to the said rotary-back-bridge-relay 55 225, thence to the side-switch contact-point 228, idle switch wiper 249, private-springs 226 and 170, side-switch-wiper 171 and contact-point 190, thence through the rotary-magnet 191 and through battery B to 60 ground G. Of course, it will be understood that the called line may be busy either by being called or by calling. In the former case a connector will be set on said line and a side-switch-wiper, similar to side-switch-wiper 202, will be in third position, whereby

the private-wiper of said connector, similar to the private-wiper 177, will be connected to ground, and, therefore, the private-contact allotted to the said line is connected to a ground terminal similar to the ground G^{13} 70 in a way that has already been dwelt upon. If the called line has been put in use by the called subscriber himself the individual-switch A^1 will be found operated so that the bank jack springs 237 and 238 75 are pressed into contact and a connection thereby established directly between ground G^{15} and the tenth contact of the second level of the private-bank 179, by way of the private-normal-conductor 195. 80 At the instant that the rotary-back-bridge-relay 225 is energized and thereby forces the springs 211, 239 and 240 into contact, the rotary-line-relay spring 187 is also connected to ground G^{13} by way of the springs 85 240 and 239, side-switch contact-point 203 to the said ground terminal G^{13} , whereby even if the rotary-line-relay 181 deenergizes and, therefore, even if the line-relay-springs 167 and 187 separate, the energizing circuit 90 for the private-magnet 188 may remain established until the rotary-back-bridge-relay 225 is deenergized. It is evident, therefore, that since the private-magnet 188, when the private-wiper 177 is on 95 a busy contact, controls the energizing circuit for the rotary-back-bridge-relay 225—and since the said rotary-back-bridge-relay, in turn, when energized provides an energizing circuit for the private-magnet 188 100 until the calling subscriber decides to release—the said private-magnet and back-bridge-relay will, so to speak, be locked in an energized condition. It will be evident, also, that as long as the private-magnet is 105 energized the side-switch will be locked in second position, since the escapement-finger 243 is retained between the escapement-teeth 244 and 245, because of the attracted condition of the private-armature 246. The 110 busy signaling circuit whereby a busy signal may be transmitted to the calling subscriber, when he calls a busy line, is completed whenever the connector is thus locked; which current also is provided by 115 the ringer-generator 205. An energizing circuit for the ringer-relay 204 is established as before, but over a slightly different circuit, since the side-switch is in this instance in second position. The energizing 120 circuit for the ringer-relay 204 may be traced from ground G^{13} at the side-switch to the contact-point 203, thence by conductor 242 and springs 239 and 211, and springs 212 and 213 to the conductor 214, 125 thence to the ringer-relay 204 and to the circuit-interrupter 206 and to the battery-lead 80 and through battery B to ground G. Each time that the ringer-relay is so energized that the springs 215 and 219 are 130

brought into contact a busy signaling current from the ringer-generator 205 of an interrupted character, corresponding to the interruption of the said ringer-relay, passes 5 to the calling substation from said ringer-generator through the springs 219 and 215, side-switch-wiper 197, contact-point 247, private-springs 248 and 226 (since the private-magnet is energized), conductor 229, 10 side-switch-wiper 249, contact-point 228, condenser 201, rotary-trunk-conductor 145, sleeve 184 of the jack 72, spring 183 to the condenser 134 of the cord-circuit D, jack-sleeve 111, rotary-trunk-conductor 100, condenser 58, springs 5 and 11 of the individual-switch A and through the primary winding 55 of the induction-coil 54, springs 12 and 6 of the individual-switch A, to the condenser 57 of the repeater C, thence over 15 the vertical-trunk-conductor 99, tip-spring 112, and through the tip supervisory relay 63 to ground G, thence to ground G¹³ at the ringer 205, through the condenser 250 to the said ringer-generator 205. But if 20 the called subscriber's line is not busy and the calling subscriber has established connection in a manner described, the bell 223 is rung until the subscriber answers. The first move is to take the receiver 251 from 25 off the switch-hook 252, which switch-hook is raised by a spring not shown, and thereby breaks connection with the contact-point 253 and closes connection instead with the contact-point 254. As a result an energizing 30 circuit is established through the rotary and vertical back-bridge-relays 225 and 255. at the connector. The energizing current for magnetizing said relays flows from ground G¹³ to the contact-point 203, side- switch-wiper 202, thence over the conductor 209, rotary-back-bridge-relay springs 210 and 211, rotary-back-bridge-relay 225, conductor 256, ringer-relay-springs 217 and 215, side-switch-wiper 197, contact-point 45 199, conductor 257, rotary-line-wiper 176, rotary-trunk-conductor 194, rotary-line-conductor 224, primary winding 258 of the induction-coil 259, transmitter 260, contact-point 254, switch-hook 252, vertical-line-conductor 221, vertical-normal-conductor 50 193, vertical-line-wiper 175, conductor 261, contact-point 198, side-switch-wiper 196, ringer-relay-springs 216 and 218, conductor 262, vertical-back-bridge-relay 255, differential-relay springs 263 and 264 to the battery-lead 80, and through the battery B to ground G. The springs 210, 211 and 239 of the rotary-back-bridge-relay 225 are so 55 adjusted that when the said relay is energized the said springs come into contact before the spring 211 leaves the spring 210. The object in this construction is to maintain the energizing circuit, just described, over the said relays 255 and 225 unbroken 60 while a section of the said circuit described 65 is substituted by a new section—that is, the connection between the spring 211 and the ground G¹³ after the said relay 225 is energized is established by connection with the spring 239 instead of with the spring 210 70 and a new connection to ground is as follows: from the said spring 211 to the spring 239, thence over the conductor 242 to the contact-point 203 and to ground G¹³. As soon as the back-bridge-relay 255 is energized, as described, the energizing circuit for the ringer-relay 204 is destroyed at a point between the vertical-back-bridge-relay springs 213 and 212 over which former 75 the said ringer-relay is directly connected. 80 Also, the spring 186 which is normally connected with the non-grounded terminal of battery B through the spring 187 is shifted into connection with the grounded terminal of battery B through the spring 212. The 85 effect of shifting these springs is to establish an energizing circuit through the back supervisory coil 66 at the cord-circuit D. The current is established from ground G¹³ to the rotary-back-bridge-relay spring 239, 90 thence through the spring 211 to the vertical-backbridge-relay spring 212 and through the spring 186 and through the winding 185 of the differential-relay 165 and the rotary-line-relay 181 to the rotary-trunk-conductor 145, thence to the sleeve 184 through the said relay 66, springs 265 and 266 to the conductor 123, thence to the tip spring 163 and to the vertical-trunk-conductor 144, through the vertical-line-relay 160 and winding 164 of the differential-relay 165 to the battery-lead 80 and through battery B to ground G. When the rotary-back-bridge-relay 225 is energized the 95 spring 210 is disconnected from the spring 211 to cut off all connection from the private-wiper 177 during the busy lock-out. The spring 240 in turn is provided so that the private-magnet 188 may be energized 100 during the busy lock-out, and the springs 211 and 239 are provided as a means whereby the energizing circuit through the vertical and rotary back-bridge-relays 255 and 225 may be shifted as described. Returning to the supervisory relay 66 at the cord 105 circuit D, through which an energizing current has been established, it may be stated that when the said relay becomes energized it attracts its armature 117, whereby the circuit for lighting the lamp 114 is broken. 110 The operator upon noticing that the said light is extinguished will understand that the called subscriber has answered. The said called subscriber having answered, in the above manner, may thereby establish 115 himself in connection with the calling subscriber by means for conversing. The transmitters 56 and 260 being energized, as described, and the receivers 52 and 251 being connected in series with the second- 120 125 130

ary windings 53 and 268, respectively, of the induction-coils 54 and 259 the two subscribers may communicate with each other over the following main talking circuit, in a manner well understood by those skilled in the art: from the transmitter 56 at the substation #2050 to the vertical-line-conductor 78, individual-bank springs 12 and 6, condenser 57, trunk-conductor 99, tip spring 112, condenser 133, tip spring 163, vertical-trunk-conductor 144, condenser 200, ringer-relay-springs 218 and 216, side-switch-wiper 196, contact-point 198, vertical-line-wiper 175, vertical-normal-conductor 193, vertical-line-conductor 221, switch-hook 252, contact-point 254, transmitter 260, primary winding 258 of the induction-coil 259, rotary-line-conductor 224, rotary-normal-conductor 194, rotary-line-wiper 176, contact-point 199, side-switch-wiper 197, ringer-relay-springs 215 and 217, condenser 201, rotary-trunk-conductor 145, sleeve 184, condenser 134, sleeve 111, rotary-trunk-conductor 100, condenser 58, individual-switch springs 5 and 11, rotary-line-conductor 79, primary winding 55 of the induction-coil 54 and back again to the transmitter 56. After the subscribers have communicated, if the subscriber at the substation #2050 then restores his receiver to the switch-hook he thereby destroys the energizing circuit through his transmitter 56 and also through the relays 59 and 60 of the repeater C, and as a result said relays 59 and 60 are deenergized. When the line-relay 60 deenergizes, the springs 95 and 97 separate and the vertical-back-bridge-relay 61 deenergizes as a result, but the construction is such that the line-relay-springs 89 and 90 of the vertical-line-relay 59 come into contact before the springs 91 and 105 separate. Closure of contact between said springs 89 and 90 while the springs 91 and 105 are in contact establishes a circuit through the release-magnet 2 of the individual-switch A. The current for energizing said magnet flows from ground G through the springs 105 and 91 and through the springs 89 and 90, individual-bank springs 7 and 9 to the release-magnet 2, thence to the battery-lead 80 and through battery B to ground G. When the release-magnet 2 attracts its armature 16 the catch 20 is raised above the abutment 21 of the plunger-arm 14, whereby the said catch is carried into position to engage the plunger-arm 14 by the spring 269 when the release-magnet deenergizes. The said release-magnet 2 deenergizes as soon as the relay 61 permits the springs 91 and 105 to separate, as described, at which time the spring 17 restores the release-armature 16 and causes the plunger-arm 14 to move the plunger 13 from the bank jack which the latter engages, and into normal position against the shaft 23. When the said plunger leaves the bank jack, as stated, the bank-springs 11, 12, 7 and 10 disengage from their respective springs 5, 6, 9 and 8. When the springs 89 and 90 engage the relay 62 of the repeater C is short circuited and therefore deenergized and at the same time a guarding potential from the master-switch contact-point 41 is removed, and when the springs 8 and 10 separate, the bridge-cut-off relay 4 is then restored to normal condition, and at the same time the guarding potential at the connector private-banks is removed. It will be evident that when the cut-off-relay 4 is restored the ground terminal G¹ is reconnected with the vertical-line-conductor 78, and the trip-magnet 3 is reconnected with the rotary-line-conductor 79. When the rotary-line-relay 60 of the repeater C permits the springs 95 and 97 to separate not only is the relay 61 deenergized, as described, but the supervisory relay 63 is deenergized also. Upon such deenergization said relay 63 permits the armature 121 to engage the contact 122 and at once the supervisory lamp 120 flashes up. The energizing circuit for said lamp is from ground G through the armature 121 and contact-point 122 to the lamp 120, thence to the contact-point 270 and armature 113 to the non-grounded terminal of battery B. The operator at the cord-circuit D upon seeing the light will understand that the calling subscriber has disconnected. The called subscriber upon restoring his receiver destroys the energizing circuit through the vertical and rotary-back-bridge-relays 255 and 225 previously described. When the said back-bridge-relays deenergize they, of course, restore the springs they control to normal position, so that the vertical-back-bridge-relay 255 restores the spring 186 to connection with the non-grounded terminal of battery B, at the same time destroying the connection between said spring and the ground terminal of said battery. As a result the energizing circuit through the vertical and rotary line-relays 160 and 181 and through the back supervisory relay 66 at the cord-circuit D is broken and said relays return to normal condition. The armature 117 of the supervisory relay 66 upon being released engages the contact-point 118 and a circuit is established through the back supervisory lamp 114 for lighting said lamp. The operator will, therefore, receive the signal that the called subscriber has disconnected also. She will then withdraw her plug from the jack 110 with the following result. The energizing circuit through the line-cut-off-relay 70 and through the supervisory relay 64 is destroyed. The latter relay then permits the armature 113 to leave the contact-points 270 and 119, whereby the current for the lamps 120 and 114 is cut off and the said lamps are thus retired or put out. When the cut-off-relay 75 80 85 90 95 100 105 110 115 120 125 130

relay 70 deenergizes, the armatures 102 and 103 then leave the contact-points 271 and 272 and return to normal engagement with the contact-points 101 and 104, respectively.

5 The operator then withdraws the other plug from the jack 72 and thereby permits the springs 138 and 139 to separate. The energizing current through the quick-acting relay 74 and through the lamps 140 and 141 is

10 destroyed, causing the said lamps to go out, and relay 74 is then deenergized. As a result of the deenergization of said relay 74 the armatures 146 and 148 return to normal engagement with the contact-points 152 and

15 153, respectively, and the armature 147 leaves the contact-point 149. As soon as said armature 147 and contact 149 separate the energizing current for the slow-acting relay 75 is cut off, but before the armatures 150

20 and 151 leave the contact-points 273 and 274, with which said armatures engage when the relay 75 is energized, the armatures 146 and 148 engage the contacts 152 and 153, as described. As a result electric impulses are

25 sent simultaneously to the vertical and rotary trunk-conductors 144 and 145 from the ground terminal G¹⁰. In the former conductor the impulse passes from ground G¹⁰ to the contact-point 273, thence through the armature 150 to the contact-point 152, armature 146 and to the conductor 144. In the rotary-line-conductor 145 the impulse passes from ground G¹⁰ to the contact-point 274 through the armature 151, contact-point 153

30 and armature 148 to the said conductor 145. The effect of simultaneously grounding the conductors 144 and 145 that lead to the connector is well known. The line-relays 160 and 181 become energized simultaneously, as

35 well as the differential-relay 165, the current from the conductor 144 passing through the vertical-line-relay 160 and winding 164 of the differential-relay 165 to the battery-lead 80 and through battery B to ground G.

40 From the rotary-line-conductor 145 the current passes through the rotary-line-relay 181, winding 185 of the differential-relay 165, vertical-back-bridge-relay springs 186 and 187 to the battery-lead 80, and through battery B to ground G. Upon being energized simultaneously the line-relays 160 and 181

45 press the trunk-release-springs 275 and 276 into contact at the same time that the springs 264 and 277 of the differential-relay 65 are

50 retained in contact by said relay. The concurrence of operations of said line-relays and said differential-relay, as described, sets up an energizing circuit through the connector release-magnet 278, and the current in said

55 circuit flows from ground G¹² through the springs 275 and 276 to the release-magnet 278, thence through the differential-relay springs 277 and 264 to the battery-lead 80 and through battery B to ground G. As

60 soon as the release-magnet 278 attracts its

armature 279 the double-dog 280 is struck to the right of the pivot 281, whereby the locking dogs 282 and 283 are withdrawn from the switch-shaft 174 and the side-switch K is restored to normal position, swinging 70 about the pivots 285 in the well-known manner. When the rotary locking-dog 283 leaves the longitudinal teeth 286 the coiled spring 287 at the top of the shaft 174 then returns the shaft to normal rotary position, 75 the movement continuing until the normal-post-arm 288 strikes the normal-post 289, at which time the shaft-support 290 finds the longitudinal slot 291, thus permitting the shaft to fall of its own weight to normal vertical position. Of course, as soon as the private-wiper 177 leaves the tenth contact of the second level of the private-bank 179 the energizing circuit for the cut-off-relay 231 of the individual-switch A¹ is broken, where- 80

85 by the said relay restores the springs it controls to normal condition, thus restoring the individual-switch A¹ to the direct control of the subscriber #2120 to whom said switch is allotted. Immediately after the impulses 90 are sent to the trunk-conductors 144 and 145 by the operation of the quick-acting relay 74 the armatures 150 and 151 of the slow-acting relay 75 withdraw from the contact-points 273 and 274, whereby the said impulses are cut off. As a result the energized connector relays are deenergized and the release-magnet 278 is restored to normal condition, whereby the armature 279 resumes its normal position. Therefore, as de- 95 scribed, when the calling subscriber hangs up his receiver he releases his individual-switch A, restores the energized relays of the repeater C, and causes the disconnect-lamp 120 to be lighted at the cord-circuit D. 105 When the called subscriber hangs up subsequently he causes the disconnect-lamp 114 to flash up as described. When the operator notices that both subscribers have sent in the disconnect-signal she removes her 110 plugs from the answering and calling jacks and by the latter operation causes releasing impulses to be sent to the automatic switching apparatus at the sub-central to which the subscriber #2120 belongs. The combined 115 act of the calling and called subscribers and of the central operator restores the originally involved apparatus to normal condition.

120 In the case previously assumed, in which the calling subscriber finds the called line busy and receives a busy-signal as a result, the said subscriber, of course, restores his receiver and waits until the connection can be obtained. Upon restoring his receiver, 125 and as previously described in the operation immediately preceding, he thereby restores his individual-switch A and the repeater C, as well as the supervisory relay 63, and thereby causes the disconnect-lamp 120 to 130

give the usual signal. The operator upon noticing that both lamps 120 and 114 are lighted will withdraw her plugs from the jacks, thereby causing release impulses to be sent to the automatic switches as before, whereby the release-magnet 278 of the connector may be energized with well-known results. It will be noticed that heretofore the use for the signal-relay 62 at the repeater 10 C does not appear. Said relay in fact is nothing more than a trouble supervisory relay and only comes into use in the event of certain kinds of trouble. For instance, if for some cause the subscriber's rotary-line-conductor 79 receives a momentary ground impulse in any manner the trip-magnet 3 will be energized and the plunger 13 will drop into the bank and, if opposite, into the bank jack H. As a result the springs 7 and 15 9 will be forced into contact and the said relay 62 will, therefore, be energized, as before by current flowing from ground G^a through said springs and through the release-magnet 2 to the battery-lead 80. Of course, the springs 8 and 10 will also come into contact and the cut-off-relay 4 will be energized also, but this is of no significance. When the relay 62 pulls up a ground connection is established from ground G^a 25 through the springs 98 and 97 to the rotary-trunk-conductor 100, so that the line-signal-relay 71 will be pulled up and the line-lamp 109 will be lighted. The operator will notice the signal and think, of course, that 30 some subscriber is trying to call. However, on receiving no answer she will know that the line is in trouble and will insert the calling plug d instead of the answering plug e into the jack 110, and will then press the 35 ringing-key c so that the springs 162 and 183 are forced onto the contact-points 292 and 293. Ringing current will then be projected from the generator 294 to the trunk-conductors 99 and 100 and through the vertical-back-bridge-relay 61. The current will pass from the conductor 99 through the said 40 relay 61 and through the rotary-line-relay springs 95 and 96 to the ground terminal G¹¹, thence to ground G^a and through the 45 springs 105 and 106 of the relay 62 to the springs 98 and 97 of the rotary-line-relay 60, thence to the rotary-trunk-conductor 100, sleeve 111, calling plug sleeve to the spring 183, thence to the contact-point 293 to the 50 generator 294. The pulsations from the generator 294 will cause the relay 61 to be energized, which latter will then close a circuit from ground G^a through the springs 89 and 90 to the release-magnet 2, thence to the 55 battery-lead 80 and through battery B to ground G. It is well known that when the release-magnet 2 becomes energized and de-energized the individual-switch A is then restored to normal condition. On being re- 60 stored the individual-switch A will permit

the springs 7 and 9 to separate and thereby cause the relay 62 to be again deenergized. If the rotary-line-conductor 79 instead of receiving one ground impulse is grounded permanently, then as fast as the switch A is 70 released by the operator it will again energize and the line-signal-lamp 109 will continue to burn. She will then report the matter to the switchboard attendant who will look further into the trouble. 75

Referring to Fig. 4, the following should be borne in mind. When any subscriber calls the subscriber #2120 the connection is established directly between the connector and the called line by means of the normal-conductors 193 and 194; but when the subscriber #2120 proceeds to make a call, and upon operating his individual-switch A¹, he connects the bank jack springs 295 and 296 with the springs 297 and 298, respectively, or other similar springs, which latter springs lead to a repeater similar to the repeater C. This is plainly indicated in Fig. 1. For example: When the subscriber #2050 calls the subscriber #2120 he comes 90 in through one of the repeaters c¹ among which is included the repeater C and over the cable 299 which comprises the trunk-conductors 99 and 100 at the trunking operator's board L which contains the cord-circuit D, thence through the plugs e and d and over the cable 300 which comprises the trunk-conductors 144 and 145 to the connectors M among which is included the connector E, thence to the substation #2120. 95 But when the subscriber #2120 calls he comes in and operates one of the individual-switches N among which is included the individual-switch A¹ and uses one of the repeaters f among which will be found a 100 repeater with which the springs 297 and 298 of the individual-switch A¹ are connected. If the additional sub-centrals are too many to be taken care of by one trunking operator or a combination of trunking 110 operators in one board another board O may be added, said board being a duplicate, of course, of the board L. In that case multiple jacks P will be added, so that the operator at the board L will be able to connect any 115 of the subscribers thereof with the subscribers of the twenty-five hundreds and twenty-six hundreds sub-centrals, as indicated, and so that the operator at the board O may connect the subscribers thereof with 120 the subscribers of the twenty and twenty-one hundreds sub-centrals. If any of the subscribers allotted to the sub-centrals desire connection with any of the subscribers belonging to the manual board Q, connection would then be established through the multiple jacks R in a well-known manner. The operator would plug the calling plug d in one of said multiple jack R corresponding 125 to the line desired and would then press 130

the key *c* and signal the subscriber desired. Assuming that the jack *g*, shown in Figs. 1 and 3, is the jack that is allotted to the desired line, the plug *d* is inserted therein. 5 The operator then depresses the key 301 and locks the key in the depressed condition until she is ready to destroy the connection. Upon depressing said key the bridge-cut-off relay 302 allotted to the line-jack *h* is energized, which latter then, in the usual and well-known manner, attracts the armatures 303 and 304 for well-known purposes. The current for energizing said relay 302 flows from ground G^{18} through the coil 302 to the 10 jack sleeve 305, thence to the sleeve of the plug *d*, spring 306 of the key 301, contact-point 307 and impedance-coil 136 to the battery *B*, thence through said battery to ground *G*. The operator then presses the 15 ringing-key *c* and sends current from the ringer-generator 294 through the springs 162 and 183 and through the plug *d* to the called subscriber's station. When said subscriber answers he removes his receiver 20 from the switch-hook, thereby disconnecting the ringer from across the circuit and substituting the transmitter and primary winding of the induction-coil in series with the line. As a result the supervisory relay 25 65 is energized by a flow of current through the following circuit. From the ground terminal *G* of battery *B* through the said relay 65, thence through the contact-point 308, spring 309 of the key 301 to the tip of the plug *d*, thence through the transmitter and primary winding of the called subscriber's telephone and back again to the 30 sleeve of the plug *d*, through the springs 306 and 307 of the key 301, through the impedance-coil 136 to the battery *B* and 35 through said battery to ground *G*. Said relay 65 upon attracting its armature 115 breaks the energizing circuit for the back supervisory lamp 114 and when said lamp 40 goes out the operator understands that the called subscriber has answered. When the connected subscribers are through talking and when they both restore their receivers to their switch-hooks the front and back 45 supervisory lamps are connected up as previously described, the calling subscriber at the same time releasing his individual-switch and restoring his repeater *C*. The operator then withdraws the plugs from 50 the jacks into which they have been inserted. If one of the manual subscribers connected with the board *Q* desires to connect with one of the sub-central subscribers he removes his receiver from his hook and 55 thereby, in a manner well known to those skilled in the art, operates his line signal. The operator upon answering will ascertain 60 the number of the subscriber desired. She will then press an order-key *J* to signal the proper trunking operator by causing the 65

lamp 76 to flash up. It is assumed that the manual subscriber has called for the subscriber #2120. The operator will at once know that said called subscriber's line is controlled by the trunking operator at the 70 board *L*, and will operate the proper button *J*. When the button *J* is pressed the springs 311 and 312 come into contact and the current is established through the lamp 75 76 that flows from ground G^{19} through the lamp 76, springs 313 and 314, conductor 315, springs 311 and 312 to battery *B*, thence through said battery to ground *G*. The operator will press the key 316 and thereby 80 throw her talking set into connection with the talking set *S* of the operator giving the order. The circuit connecting the two operator's sets is as follows: From the receiver 129 to the condenser 132, thence through the springs 317 and 318, conductor 85 319, springs 320 and 321 to the talking set *S* back to the springs 322 and 323, conductor 324 to the springs 325 and 326 to the secondary winding 130 of the induction-coil 131, and back to the receiver 129. When the 90 operator at the board *L* answers the operator at the board *Q* will report to her that subscriber #1050, for example, wants to connect with the subscriber #2120. The operator at the board *L* will then release the 95 button 316 and the other operator will release the key *J*. Furthermore, the operator at the board *L* will insert her answering plug *e* into the multiple jack *R* of the subscriber #1050, and with the calling plug *d* 100 will call up the desired subscriber #2120, in a manner that has been previously described, and thus establish the desired connection. Evidently, when the answering plug *e* is inserted into the multiple jack of 105 the calling subscriber the supervisory relays 63 and 64 will be energized or pulled up simultaneously, since the calling subscriber's receiver is off the hook. The back supervisory lamp 114, of course, will flash up and 110 stay thus lighted until the subscriber #2120 answers, as before described. As long as both subscribers are connected the lamps 120 and 114 will not be lighted, but when they both hang up their receivers the said lamp 115 will brighten up and signal the operator that the line is out of use. She will then withdraw the plugs from their jacks with the usual and well-known result.

I thus provide an improved telephone 120 system comprising numerous new features as set forth. I provide means by which a manual system that has reached a reasonable limit may be still further enlarged. I provide trunking boards for said manual exchange in which trunk-line terminate that 125 connect sub-centrals with the main-central and means whereby subscribers in these sub-centrals may communicate with each other and with the subscribers of the main manual 130

exchange and vice versa. I provide an improved cord-circuit for the trunking boards that facilitates the establishment of any of the aforesaid connections, and with apparatus for working the automatic switches that must be operated in establishing a connection. I provide separate means also in connection with the outgoing trunk-lines whereby the automatic switches may be automatically released without any special effort on the part of the operator. I also provide a highly efficient repeater for the purpose set forth. I provide means at the trunking boards whereby if one operator at one board occupies one of the outgoing trunks a signal is established at all other multiple boards to notify all other operators that said trunk is busy, as clearly illustrated.

20. The resistance of the various coils in this system may be varied, but good results are obtained when they are wound as follows: coil 62, 4000 ohms; coil 4, 1800 ohms; coil 71, 200 ohms; coils 24, 61, 70, 74, 75 and 204, 500 ohms each; coils 59, 60 and 188, 350 ohms each; coils 2, 3, 26, 191, 168 and 278, 60 ohms each; coils 63, 64, 65, 66 and 136, 100 ohms each; coils 160 and 181, 150 ohms each; coils 225 and 255, 375 ohms each; 30 windings of the differential-relay 25, 500 ohms each; windings 164 and 185 of the differential-relay 165, 350 ohms each. The battery may be of 50 volts.

With my improved arrangement it will be seen that I make it possible for a manual board operator to receive calls through automatic trunk-selecting switching machinery, and to then establish connection with the called subscriber's line either manually or semi-automatically, according to whether the called subscriber's line terminates directly at her board or in the multiple-jacks of the connector-banks at a sub-central station. Thus, if the connection with the called subscriber's line must be made through the medium of a connector, it is evident that the number-impulses for operating the connector are transmitted by the switchboard operator. Thus, in any case all a calling subscriber does is to simply take down his receiver and give his order in the usual manner. The taking down of his receiver constitutes the expedient by which he automatically operates his individual-switch to obtain trunk-line connection with the main or central station, providing, of course, that his line terminates at a sub-central station. Calling subscribers whose lines terminate directly in answering-jacks on the manual boards will make their calls in the same manner, at least as far as they are concerned, but in such case there is, of course, no automatic trunk-selecting operation to obtain connection with the switchboard operator. The calling subscriber re-

leases his individual-switch and restores the repeater when he hangs up his receiver, and the manual board operator restores the connector when she withdraws the plug from the jack connected with the trunk-line. As shown, the electric current for both switching and talking purposes is supplied from the common battery or centralized source of current supply B. Thus, the common battery is used for feeding talking current through the repeater-relays and through the individual-switch to the calling line, and through the connector-relays and the connector-switch to the called line. The battery is bridged across the cord-circuit, but the circuits for charging the subscriber's microphone transmitters do not include any portion of the cord-circuit.

With the individual-switch mechanism shown and described, it will be seen that each calling subscriber gets connection with the first idle trunk-line next in order after the trunk-line last put in use. For example, if the fifth trunk-line was the one last used by the calling subscriber, the subscriber who makes the next call will then obtain connection with the sixth trunk-line. In each case therefore, a calling subscriber takes a pre-selected trunk-line, and at the same time automatically selects the next idle trunk-line for use by the subscriber making the next call. In other words, a subscriber does not select his own trunk-line, but simply takes the one already selected for him, and in each case the calling subscriber merely takes the trunk-line ready and waiting for him and selects another for the next calling subscriber.

What I claim as my invention is:—

1. A telephone exchange system comprising a repeater, a calling subscriber's line, a subscriber's telephone, a switch individual to said line and controllable from the subscriber's telephone, a release-circuit for conducting current to restore the said individual-switch, provided with a normally-closed switch-point, the said switch adapted for connecting the subscriber's line with the repeater, and said repeater provided with a relay for controlling said switch-point in the release-circuit, said relay being connected to supply talking current to said calling line during conversation.

2. A telephone exchange system comprising a calling subscriber's line, a subscriber's telephone, a repeater, an individual-switch for said line, controllable by the subscriber, adapted for connecting the line with the said repeater, a main or central station, a trunk-line connecting the repeater with the said main or central station, a line signal individual to said trunk-line, said repeater provided with a relay adapted to respond to trouble on the line and operate said line signal.

3. A telephone exchange system comprising a repeater, a calling subscriber's line, a subscriber's telephone, a line-switch controlled by the subscriber, adapted to connect 5 the subscriber's line with the repeater, a main or central station, a trunk-line connecting the repeater with the said main or central station, a line signal individual to said trunk-line, adapted to be operated 10 when the subscriber's line and repeater are connected, a circuit for conducting current for said line signal, a line-relay for controlling said circuit, an energizing circuit for said line-relay, said repeater provided 15 with another relay for controlling said energizing circuit.

4. A telephone exchange system comprising a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to said trunk-line, controllable from 20 the repeater, and means whereby said signal is responsive to trouble on the line.

5. A telephone exchange system comprising a repeater, a calling subscriber's line, a subscriber's telephone, a line-switch controllable by the subscriber, adapted for connecting the subscriber's line with the repeater, a main or central station, a trunk-line connecting the repeater with the said main or 35 central station, and a line signal individual to the trunk-line, controllable from said repeater, responsive to incoming calls.

6. A telephone exchange system comprising a repeater, a calling subscriber's line, a subscriber's telephone, a line-switch controllable by the subscriber, adapted for connecting the repeater with the subscriber's line, a main or central station, a trunk-line connecting the repeater with the main or 45 central station, a line signal relay individual to said trunk-line, a cut-off-relay provided with armatures for said trunk-line, a line signal relay energizing circuit including said armatures, said repeater provided 50 with a relay and switch-contacts, and means for closing said switch-contacts to energize the repeater relay, as set forth.

7. A telephone exchange system comprising a repeater, a calling subscriber's line, a subscriber's telephone, a line-switch controllable by the subscriber, adapted for connecting the subscriber's line with the repeater, a main or central station, a trunk-line connecting the repeater with the said main or 55 central station, a line signal relay individual to the trunk-line, a cut-off-relay provided with armatures for said trunk-line, an energizing circuit for said line signal relay comprising one of said armatures, said repeater provided with normally open switch- 60

contacts, and means for closing said normally open switch-contacts to energize said line signal relay.

8. A telephone exchange system comprising a repeater, a calling subscriber's line, a subscriber's telephone, an individual line-switch controllable by the subscriber, a subscriber's device for transmitting an electric impulse for operating said switch, said switch adapted for connecting the subscriber's line with the repeater, a line-switch release-circuit comprising normally closed switch-contacts, and normally open switch-contacts, a main or central station, a trunk-line connecting the repeater with the 75 said main or central station, said repeater provided with a relay, a relay energizing circuit comprising a conductor of said trunk-line, including also a pair of normally closed switch-contacts at the repeater, and a 80 suitable return circuit, the said normally open release-circuit switch-contacts being controlled by the said repeater relay, the said relay energizable to cause said release-circuit to release or restore the line-switch. 90

9. A telephone exchange system comprising a repeater, a calling subscriber's line, a subscriber's telephone, an individual line-switch operable by the subscriber, adapted for connecting the subscriber's line with the repeater, said repeater provided with a pair 95 of relays, and an energizing circuit for said relays, comprising the relays in series with the subscriber's line-conductors.

10. A telephone exchange system comprising a repeater, a calling subscriber's line, a subscriber's telephone, an individual line-switch operable by the subscriber, adapted for connecting the subscriber's line with the repeater, said repeater provided 100 with a pair of relays, and an energizing circuit for said relays, comprising the relay-windings in series with the subscriber's telephone.

11. A telephone exchange system comprising a repeater, a calling subscriber's line, a subscriber's telephone, a subscriber's switch-hook, a subscriber's induction-coil, an individual line-switch operable by the subscriber, adapted for connecting the subscriber's line with the repeater, said repeater provided with a pair of relays, and an energizing circuit for said relays, comprising the relays in series with the switch-hook and 115 a winding of said induction-coil. 120

12. A telephone exchange system comprising a repeater, a calling subscriber's line, a subscriber's telephone, an individual line-switch operable by the subscriber, a main or central station, a trunk-line leading 125 through the repeater to the main or central station, said line-switch adapted to connect the subscriber's line with the trunk-line, said repeater provided with means for dividing the trunk-line into inductively connected 130

sections, a battery having one pole grounded, said repeater provided with a relay normally connected with the non-grounded pole of the battery, the other terminal of the relay being connected with one of the trunk-line-conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual-switch.

13. In an automatic and manual telephone exchange system, the combination of a repeater, a calling subscriber's line, a subscriber's telephone, a switch individual to said line and controllable from the subscriber's telephone, a release-circuit for conducting current to restore the said individual-switch, provided with a normally closed switch-point, the said switch adapted for connecting the subscriber's line with the repeater, said repeater provided with a relay for controlling said switch-point in the release-circuit, other subscribers' telephone lines, multiple-jacks for said other subscribers' lines, and switchboard cords and plugs for completing connection between said calling subscriber's line and any one of said other telephone lines.

14. In an automatic and manual telephone exchange system, the combination of a calling subscriber's line, a subscriber's telephone, a repeater, an individual-switch for said line, controllable by the subscriber, adapted for connecting the line with said repeater, a main or central station, a trunk-line connecting the repeater with the said main or central station, a line signal individual to said trunk-line, said repeater provided with a relay adapted to respond to trouble on the line and operate said line signal, other subscribers' telephone lines, multiple-jacks for said other subscribers' lines, and switchboard cords and plugs for completing connection between said calling subscriber's line and any one of said other telephone lines.

15. In an automatic and manual telephone exchange system, the combination of a repeater, a calling subscriber's line, a subscriber's telephone, a line-switch controlled by the subscriber, adapted to connect the subscriber's line with the repeater, a main or central station, a trunk-line connecting the repeater with the said main or central sta-

tion, a line signal individual to said trunk-line, adapted to be operated when the subscriber's line and repeater are connected, a circuit for conducting current for said line signal, a line-relay for controlling said circuit, an energizing circuit for said line-relay, said repeater provided with a relay for controlling said energizing circuit, other subscribers' telephone lines, multiple-jacks for said other subscribers' lines, and switchboard cords and plugs for completing connection between said calling subscriber's line and any one of said other telephone lines.

16. In an automatic and manual telephone exchange system, the combination of a repeater, a calling subscriber's line, a subscriber's telephone, a line-switch controllable by the subscriber, adapted for connecting the subscriber's line with the repeater, a main or central station, a trunk-line connecting the repeater with said main or central station, a line signal individual to said trunk-line, controllable from the repeater, and means whereby said signal is responsive to trouble on the line, other subscribers' telephone lines, multiple-jacks for said other subscribers' lines, and switchboard cords and plugs for completing connection between said calling subscriber's line and any one of said other telephone lines.

17. In an automatic and manual telephone exchange system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to the trunk-line, controllable from said repeater, responsive to incoming calls, other subscribers' telephone lines, multiple-jacks for said other subscribers' lines, and switch board cords and plugs for completing connection between said calling subscriber's line and any one of said other telephone lines.

18. In an automatic and manual telephone exchange system, the combination of a repeater, a calling subscriber's line, a subscriber's telephone, a line-switch controllable by the subscriber, adapted for connecting the repeater with the subscriber's line, a main or central station, a trunk-line connecting the repeater with the main or central station, a line signal relay individual to said trunk-line, a cut-off-relay provided with armatures for said trunk line, a line signal relay energizing circuit including said armatures, said repeater provided with a relay and a pair of switch-contacts, means for closing said switch-contacts to energize the repeater relay, other subscribers' telephone lines, multiple-jacks for said other subscribers' lines, and switch board cords and

plugs for completing connection between said calling subscriber's line and any one of said other telephone lines.

19. In an automatic and manual telephone exchange system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal relay individual to the trunk-line, a cut-off-relay provided with armatures for said trunk-line, an energizing circuit for said line signal relay comprising one of said armatures, said repeater provided with a pair of normally open switch-contacts, means for closing said normally open switch-contacts to energize said line signal relay, other subscribers' telephone lines, multiple-jacks for said other subscribers' lines, and switchboard cords and plugs for completing connection between said calling subscriber's line and any one of said other telephone lines.

20. In an automatic and manual telephone exchange system, the combination of a repeater, a calling subscriber's line, a subscriber's telephone, a switch individual to the subscriber's line, controllable from the telephone, a release-circuit for conducting current for releasing or restoring said individual-switch, said switch adapted for connecting the subscriber's line with the repeater, said repeater provided with a pair of normally closed switch-contacts and normally open switch-contacts included in said circuit, means for closing the said normally open switch-contacts to send current over the release-circuit to restore the individual-switch, other subscribers' telephone lines, multiple-jacks for said other subscribers' lines, and switchboard cords and plugs for completing connection between said calling subscriber's line and any one of said other telephone lines.

21. In an automatic and manual telephone exchange system, the combination of a repeater, a calling subscriber's line, a subscriber's telephone, an individual line-switch controllable by the subscriber, a subscriber's device for transmitting an electric impulse for operating said switch, said switch adapted for connecting the subscriber's line with the repeater, a line-switch release-circuit comprising normally closed switch-contacts, and normally open switch-contacts, a main or central station, a trunk-line connecting the repeater with the said main or central station, said repeater provided with a relay, a relay energizing circuit comprising a conductor of said trunk-line, including also normally closed switch-contacts at the repeater, and a suitable return circuit, the

said normally open release-circuit switch-contacts being controlled by the said repeater relay, the said relay energizable to cause said release-circuit to release or restore the line-switch, other subscribers' telephone lines, multiple-jacks for said other subscribers' lines, and switchboard cords and plugs for completing connection between said calling subscriber's line and any one of said other telephone lines.

22. In an automatic and manual telephone exchange system, the combination of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relays in series with the subscriber's line-conductors, other subscribers' telephone lines, multiple-jacks for said other subscribers' lines, and switchboard cords and plugs for completing connection between said calling subscriber's line and any one of said other telephone lines.

23. In an automatic and manual telephone exchange system, the combination of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relay-windings in series with the subscriber's telephone, other subscribers' telephone lines, multiple-jacks for said other subscribers' lines, and switchboard cords and plugs for completing connection between said calling subscriber's line and any one of said other telephone lines.

24. In an automatic and manual telephone exchange system, the combination of a repeater, a calling subscriber's line, a subscriber's telephone, a subscriber's switch-hook, a subscriber's induction-coil, an individual line-switch operable by the subscriber, adapted for connecting the subscriber's line with the repeater, said repeater provided with a pair of relays, an energizing circuit for said relays, comprising the relays in series with the switch-hook and a winding of said induction-coil, other subscribers' telephone lines, multiple-jacks for said other subscribers' lines, and switchboard cords and plugs for completing connection between said calling subscriber's line and any one of said other telephone lines.

25. In an automatic and manual telephone exchange system, the combination of a repeater, a calling subscriber's line, a subscriber's telephone, an individual line-switch operable by the subscriber, a main or

central station, a trunk-line leading through the repeater to the main or central station, said line-switch adapted to connect the subscriber's line with the trunk-line, said repeater provided with means for dividing the trunk-line into inductively connected sections, a battery having one pole grounded, said repeater provided with a relay normally connected with the non-grounded pole of the battery, the other terminal of the relay being connected with one of the trunk-line-conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual-switch, other subscribers' telephone lines, multiple-jacks for said other subscribers' lines, and switchboard cords and plugs for completing connection between said calling subscriber's line and any one of said other telephone lines.

26. The combination, in a semi-automatic telephone trunking system, of a repeater, a calling subscriber's line, a subscriber's telephone, a switch individual to said line and controllable from the subscriber's telephone, a release-circuit for conducting current to restore the said individual-switch, provided with a normally closed switch-point, the said switch adapted for connecting the subscriber's line with the repeater, said repeater provided with a relay for controlling said switch-point in the release-circuit, other subscribers' telephone lines, a manual switchboard, and connectors controllable by the operator at said manual switchboard, adapted for completing connection between said calling subscriber's line and any one of said other telephone lines.

27. The combination, in a semi-automatic telephone trunking system, of a calling subscriber's line, a subscriber's telephone, a repeater, an individual-switch for said line, controllable by the subscriber, adapted for connecting the line with the said repeater, a main or central station, a trunk line connecting the repeater with the said main or central station, a line signal individual to said trunk-line, said repeater provided with a relay adapted to respond to trouble on the line and operate said line signal, other subscribers' telephone lines, a manual switchboard, and connectors controllable by the operator at said manual switchboard, adapted for completing connection between said calling subscriber's line and any one of said other telephone lines.

said calling subscriber's line and any one of said other telephone lines.

28. The combination, in a semi-automatic telephone trunking system, of a repeater, a calling subscriber's line, a subscriber's telephone, a line-switch controlled by the subscriber, adapted to connect the subscriber's line with the repeater, a main or central station, a trunk-line connecting the repeater with the said main or central station, a line signal individual to said trunk-line, adapted to be operated when the subscriber's line and repeater are connected, a circuit for conducting current for said line signal, a line-relay for controlling said circuit, an energizing circuit for said line-relay, said repeater provided with a relay for controlling said energizing circuit, other subscribers' telephone lines, a manual switchboard, and connectors controllable by the operator at said manual switchboard, adapted for completing connection between said calling subscriber's line and any one of said other telephone lines.

29. The combination, in a semi-automatic telephone trunking system, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to said trunk-line, controllable from the repeater, and means whereby said signal is responsive to trouble on the line, other subscribers' telephone lines, a manual switchboard, and connectors controllable by the operator at said manual switchboard, adapted for completing connection between said calling subscriber's line and any one of said other telephone lines.

30. The combination, in a semi-automatic telephone trunking system, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to the trunk-line, controllable from the repeater, responsive to incoming calls, other subscribers' telephone lines, a manual switchboard, and connectors controllable by the operator at said manual switchboard, adapted for completing connection between said calling subscriber's line and any one of said other telephone lines.

31. The combination, in a semi-automatic telephone trunking system, of a repeater, a calling subscriber's line, a subscriber's telephone, a line-switch controllable by the subscriber, adapted for connecting the repeater with the subscriber's line, a main or central

- station, a trunk-line connecting the repeater with the main or central station, a line signal relay individual to said trunk-line, a cut-off-relay provided with armatures for said 5 trunk-line, a line signal relay energizing circuit including said armatures, said repeater provided with a relay and switch-contacts, means for closing said switch-contacts to energize the repeater relay, other subscribers' 10 telephone lines, a manual switchboard, and connectors controllable by the operator at said manual switchboard, adapted for completing connection between said calling subscriber's line and any one of said other 15 telephone lines.
32. The combination, in a semi-automatic telephone trunking system, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal relay individual to the 20 trunk-line, a cut-off-relay provided with armatures for said trunk-line, an energizing circuit for said line signal relay comprising one of said armatures, said repeater provided with normally open switch-contacts, means for closing said normally open switch-contacts to energize said line signal relay, other subscribers' telephone lines, a manual switchboard, and connectors controllable by the operator at said manual 25 switchboard, adapted for completing connection between said calling subscriber's line and any one of said other telephone lines.
33. The combination, in a semi-automatic telephone trunking system, of a repeater, a calling subscriber's line, a subscriber's telephone, a switch individual to the subscriber's line, controllable from the telephone, a release-circuit for conducting current for releasing or restoring said individual-switch, said switch adapted for connecting the subscriber's line with the repeater, said repeater provided with normally closed switch-contacts and normally open switch-contacts included in said circuit, means for 30 closing the said normally open switch-contacts to send current over the release-circuit to restore the individual-switch, other subscriber's telephone lines, a manual switchboard, and connectors controllable by the operator at said manual switchboard, adapted for completing connection between said calling subscriber's line and any one of said other telephone lines.
34. The combination, in a semi-automatic telephone trunking system, of a repeater, a calling subscriber's line, a subscriber's telephone, an individual line-switch controllable by the subscriber, a subscriber's device for transmitting an electric impulse for operating said switch, said switch adapted for 35 connecting the subscriber's line with the repeater, a line-switch release-circuit comprising normally closed switch-contacts, and normally open switch-contacts, a main or central station, a trunk-line connecting the repeater with the said main or central station, said repeater provided with a relay, a relay energizing circuit comprising a conductor of said trunk-line, including also normally closed switch-contacts, at the repeater, 40 and a suitable return circuit, the said normally open release-circuit switch contacts being controlled by the said repeater relay, the said relay energizable to cause said release-circuit to release or restore the line-switch, other subscribers' telephone lines, a manual switchboard, and connectors controllable by the operator at said manual switchboard, adapted for completing connection between said calling subscriber's line and any one of 45 said other telephone lines.
35. The combination, in a semi-automatic telephone trunking system, of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relays in series with the subscriber's 50 line-conductors, other subscribers' telephone lines, a manual switchboard, and connectors controllable by the operator at said manual switchboard, adapted for completing connection between said calling subscriber's line and any one of 55 said other telephone lines.
36. The combination, in a semi-automatic telephone trunking system, of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relay-windings in series with the subscriber's telephone, other subscribers' telephone lines, a manual switchboard, and connectors controllable by the operator at 60 said manual switchboard, adapted for completing connection between said calling subscriber's line and any one of said other telephone lines.
37. The combination, in a semi-automatic telephone trunking system, of a repeater, a calling subscriber's line, a subscriber's telephone, a subscriber's switch-hook, a subscriber's induction-coil, an individual line-switch operable by the subscriber, adapted for connecting the subscriber's line with the 65 repeater, said repeater provided with a pair of relays, an energizing circuit for said relays, comprising the relays in series with the switch-hook and a winding of said induction-coil, other subscribers' telephone lines,

a manual switchboard, and connectors controllable by the operator at said manual switchboard, adapted for completing connection between said calling subscriber's line and any one of said other telephone lines.

38. The combination, in a semi-automatic telephone trunking system, of a repeater, a calling subscriber's line, a subscriber's telephone, an individual line-switch operable by the subscriber, a main or central station, a trunk-line leading through the repeater to the main or central station, said line-switch adapted to connect the subscriber's line with the trunk-line, said repeater provided with means for dividing the trunk-line into inductively connected sections, a battery having one pole grounded, said repeater provided with a relay normally connected with the non-grounded pole of the battery, the other terminal of the relay being connected with one of the trunk-line-conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual-switch, other subscribers' telephone lines, a manual switchboard, and connectors controllable by the operator at said manual switchboard, adapted for completing connection between said calling subscriber's line and any one of said other telephone lines.

39. In an automatic and manual telephone trunking system, the combination of a repeater, a calling subscriber's line, a subscriber's telephone, a switch individual to said line and controllable from the subscriber's telephone, a release-circuit for conducting current to restore the said individual-switch, provided with a normally closed switch-point, the said switch adapted for connecting the subscriber's line with the repeater, said repeater provided with a relay for controlling said switch-point in the release-circuit, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

40. In an automatic and manual telephone trunking system, the combination of a call-

ing subscriber's line, a subscriber's telephone, a repeater, an individual-switch for said line, controllable by the subscriber, adapted for connecting the line with the said repeater, a main or central station, a trunk-line connecting the repeater with the said main or central station, a line signal individual to said trunk-line, said repeater provided with a relay adapted to respond to trouble on the line and operate said line signal, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

41. In an automatic and manual telephone trunking system, the combination of a repeater, a calling subscriber's line, a subscriber's telephone, a line-switch controlled by the subscriber, adapted to connect the subscriber's line with the repeater, a main or central station, a trunk-line connecting the repeater with the said main or central station, a line signal individual to said trunk-line, adapted to be operated when the subscriber's line and repeater are connected, a circuit for conducting current for said line signal, a line-relay for controlling said circuit, an energizing circuit for said line-relay, said repeater provided with a relay for controlling said energizing circuit, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

42. In an automatic and manual telephone trunking system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to said trunk-line, controllable from the repeater, and means whereby said signal is responsive to trouble on the line, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

43. In an automatic and manual telephone

- trunking system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to the trunk-line, controllable from said repeater, responsive to incoming calls, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.
44. In an automatic and manual telephone trunking system, the combination of a repeater, a calling subscriber's line, a subscriber's telephone, a line-switch controllable by the subscriber, adapted for connecting the repeater with the subscriber's line, a main or central station, a trunk-line connecting the repeater with the main or central station, a line signal relay individual to said trunk-line, a cut-off-relay provided with armatures for said trunk-line, a line signal relay energizing circuit including said armatures, said repeater provided with a relay and switch-contacts, means for closing said switch-contacts to energize the repeater relay, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.
45. In an automatic and manual telephone trunking system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal relay individual to the trunk-line, a cut-off-relay provided with armatures for said trunk-line, an energizing circuit for said line signal relay comprising one of said armatures, said repeater provided with normally open switch-contacts, means for closing said normally open switch-contacts to energize said line signal relay, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal

apparatus for said cord-circuits, controlled by the calling and called subscribers.

46. In an automatic and manual telephone trunking system, the combination of a repeater, a calling subscriber's line, a subscriber's telephone, a switch individual to the subscriber's line, controllable from the telephone, a release-circuit for conducting current for releasing or restoring said individual-switch, said switch adapted for connecting the subscriber's line with the repeater, said repeater provided with normally closed switch-contacts and normally open switch-contacts included in said circuit, means for closing the said normally open switch-contacts to send current over the release-circuit to restore the individual-switch, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

47. In an automatic and manual telephone trunking system, the combination of a repeater, a calling subscriber's line, a subscriber's telephone, an individual line-switch controllable by the subscriber, a subscriber's device for transmitting an electric impulse for operating said switch, said switch adapted for connecting the subscriber's line with the repeater, a line-switch release-circuit comprising normally closed switch-contacts, and normally open switch-contacts, a main or central station, a trunk-line connecting the repeater with the said main or central station, said repeater provided with a relay, a relay energizing circuit comprising a conductor of said trunk-line, including also normally closed switch-contacts at the repeater, and a suitable return circuit, the said normally open release-circuit switch-contacts being controlled by the said repeater relay, the said relay energizable to cause said release-circuit to release or restore the line-switch, other subscriber's telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

48. In an automatic and manual telephone trunking system, the combination of a repeater, a calling subscriber's line, a subscriber's telephone, an individual line-switch operable by the subscriber, adapted for connecting the subscriber's line with the repeater, said repeater provided with a pair of relays, an energizing circuit for said re-

lays, comprising the relays in series with the subscriber's line-conductors, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

49. In an automatic and manual telephone trunking system, the combination of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relay-windings in series with the subscriber's telephone, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

50. In an automatic and manual telephone trunking system, the combination of a repeater, a calling subscriber's line, a subscriber's telephone, a subscriber's switch-hook, a subscriber's induction-coil, an individual line-switch operable by the subscriber, adapted for connecting the subscriber's line with the repeater, said repeater provided with a pair of relays, an energizing circuit for said relays, comprising the relays in series with the switch-hook and a winding of said induction-coil, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

51. In an automatic and manual telephone trunking system, the combination of a repeater, a calling subscriber's line, a subscriber's telephone, an individual line-switch operable by the subscriber, a main or central station, a trunk-line leading through the repeater to the main or central station, said line-switch adapted to connect the subscriber's line with the trunk-line, said repeater provided with means for dividing the trunk-line into inductively connected sections, a battery having one pole grounded, said repeater provided with a relay normally connected with the non-grounded pole

of the battery, the other terminal of the relay being connected with one of the trunk-line-conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual-switch, other subscribers' telephone lines, outgoing trunk-lines, connectors for connecting any outgoing trunk-line with any one of said other telephone lines, cord-circuits for completing connection between the calling subscriber's line and any one of said outgoing trunk-lines, and supervisory signal apparatus for said cord-circuits, controlled by the calling and called subscribers.

52. The combination, in a semi-automatic telephone and supervisory system, of a repeater, a calling subscriber's line, a subscriber's telephone, a switch individual to said line and controllable from the subscriber's telephone, a release-circuit for conducting current to restore the said individual-switch, provided with a normally closed switch-point, the said switch adapted for connecting the subscriber's line with the repeater, said repeater provided with a relay for controlling said switch-point in the release-circuit, other subscribers' telephone lines, multiple-jacks for said other telephone lines, cords and plugs adapted to cooperate with said jacks in completing connection between the calling subscriber's line and any one of said other telephone lines, and supervisory signal apparatus associated with said cords, adapted to be controlled by the calling and called subscribers.

53. The combination, in a semi-automatic telephone and supervisory system, of a calling subscriber's line, a subscriber's telephone, a repeater, an individual-switch for said line, controllable by the subscriber, adapted for connecting the line with the said repeater, a main or central station, a trunk-line connecting the repeater with the said main or central station, a line signal individual to said trunk-line, said repeater provided with a relay adapted to respond to trouble on the line and operate said line signal, other subscribers' telephone lines, multiple-jacks for said other telephone lines, cords and plugs adapted to cooperate with said jacks in completing connection between the calling subscriber's line and any one of said other telephone lines,

and supervisory signal apparatus associated with said cords, adapted to be controlled by the calling and called subscribers.

54. The combination, in a semi-automatic telephone and supervisory system, of a repeater, a calling subscriber's line, a subscriber's telephone, a line-switch controllable by the subscriber, adapted to connect the subscriber's line with the repeater, a main or central station, a trunk-line connecting the repeater with the said main or central station, a line signal individual to said trunk-line, adapted to be operated when the subscriber's line and repeater are connected, a circuit for conducting current for said line signal, a line-relay for controlling said circuit, an energizing circuit for said line-relay, said repeater provided with a relay for controlling said energizing circuit, other subscribers' telephone lines, multiple-jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers.

55. The combination, in a semi-automatic telephone and supervisory system, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to said trunk-line controllable from the repeater, and means whereby said signal is responsive to trouble on the line, other subscribers' telephone lines, multiple-jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers.

56. The combination, in a semi-automatic telephone and supervisory system, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to the trunk-line, controllable from said repeater, responsive to incoming calls, other subscribers' telephone lines, multiple-jacks for said other telephone lines, cords and plugs adapted to coöperate with said jacks in completing connection between the calling subscriber's line and any one of said

other telephone lines, and supervisory signal apparatus associated with said cords, adapted to be controlled by the calling and called subscribers.

57. The combination, in a semi-automatic telephone and supervisory system, of a repeater, a calling subscriber's line, a subscriber's telephone, a line-switch controllable by the subscriber, adapted for connecting the repeater with the subscriber's line, a main or central station, a trunk-line connecting the repeater with the main or central station, a line signal relay individual to said trunk-line, a cut-off-relay provided with armatures for said trunk-line, a line signal relay energizing circuit including said armatures, said repeater provided with a relay and switch-contacts, means for closing said switch-contacts to energize the repeater relay, other subscribers' telephone lines, multiple-jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers.

58. The combination, in a semi-automatic telephone and supervisory system, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal relay individual to the trunk line, a cut-off-relay provided with armatures for said trunk-line, an energizing circuit for said line signal relay comprising one of said armatures, said repeater provided with normally open switch-contacts, means for closing said normally open switch-contacts to energize said line signal relay, other subscribers' telephone lines, multiple-jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers.

59. The combination, in a semi-automatic telephone and supervisory system, of a repeater, a calling subscriber's line, a subscriber's telephone, a switch individual to the subscriber's line, controllable from the telephone, a release-circuit for conducting current for releasing or restoring said individual-switch, said switch adapted for connecting the subscriber's line with the repeater, said repeater provided with normally closed switch-contacts and normally open switch-contacts included in said circuit, means for closing the said normally open switch-contacts

to send current over the release-circuit to restore the individual-switch, other subscribers' telephone lines, multiple-jacks for said other telephone lines, cords and plugs 5 adapted to coöperate with said jacks in completing connection between the calling subscriber's line and any one of said other telephone lines, and supervisory signal apparatus associated with said cords, adapted to be 10 controlled by the calling and called subscribers.

60. The combination, in a semi-automatic telephone and supervisory system, of a repeater, a calling subscriber's line, a subscriber's telephone, an individual line-switch controllable by the subscriber, a subscriber's device for transmitting an electric impulse for operating said switch, said switch adapted for connecting the subscriber's line with 15 the repeater, a line-switch release-circuit comprising normally closed switch contacts and normally open switch-contacts, a main or central station, a trunk-line connecting the repeater with the said main or central station, 20 said repeater provided with a relay, a relay energizing circuit comprising a conductor of said trunk-line, including also normally closed switch-contacts at the repeater, and a suitable return circuit, the said normally 25 open release-circuit switch contacts being controlled by the said repeater relay, the said relay energizable to cause said release-circuit to release or restore the line-switch, other subscribers' telephone lines, multiple- 30 jacks for said other telephone lines, cords and plugs adapted to coöperate with said jacks in completing connection between the calling subscriber's line and any one of said other telephone lines, and supervisory signal 35 apparatus associated with said cords, adapted to be controlled by the calling and called subscribers.

61. The combination, in a semi-automatic telephone and supervisory system, of a repeater, a calling subscriber's line, a subscriber's telephone, an individual line-switch operable by the subscriber, adapted for connecting the subscriber's line with the repeater, said repeater provided with a pair 40 of relays, an energizing circuit for said relays, comprising the relays in series with the subscriber's line-conductors, other subscribers' telephone lines, multiple-jacks for said other telephone lines, cords and plugs 45 adapted to coöperate with said jacks in completing connection between the calling subscriber's line and any one of said other telephone lines, and supervisory signal apparatus associated with said cords, adapted to be controlled by the calling and called subscribers.

62. The combination, in a semi-automatic telephone and supervisory system, of a repeater, a calling subscriber's line, a subscriber's telephone, an individual line-switch

operable by the subscriber, adapted for connecting the subscriber's line with the repeater, said repeater provided with a pair of relays, an energizing circuit for said relays, comprising the relay-windings in series 70 with the subscriber's telephone, other subscribers' telephone lines, multiple jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers. 75

63. The combination, in a semi-automatic telephone and supervisory system, of a repeater, a calling subscriber's line, a subscriber's telephone, a subscriber's switch-hook, a subscriber's induction-coil, an individual line-switch operable by the subscriber, adapted for connecting the subscriber's line with the repeater, said repeater provided with a pair of relays, an energizing circuit for said relays, comprising the relays in 80 series with the switch-hook and a winding of said induction-coil, other subscribers' telephone lines, multiple-jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers. 85

64. The combination, in a semi-automatic telephone and supervisory system, of a repeater, a calling subscriber's line, a subscriber's telephone, an individual line-switch operable by the subscriber, a main or central station, a trunk-line leading through the repeater to the main or central station, said line-switch adapted to connect the subscriber's line with the trunk-line, said repeater provided with means for dividing the 90 trunk-line into inductively connected sections, a battery having one pole grounded, said repeater provided with a relay normally connected with the non-grounded pole of the battery, the other terminal of the relay being connected with one of the trunk-line conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual line-switch. 95

- vidual-switch, other subscribers' telephone lines, multiple-jacks for said other telephone lines, cords and plugs adapted to coöperate with said jacks in completing connection between the calling subscriber's line and any one of said other telephone lines, and supervisory signal apparatus associated with said cords, adapted to be controlled by the calling and called subscribers. 5
- 10 65. In an automatic and manual telephone trunking and release system, the combination of a repeater, a calling subscriber's line, a subscriber's telephone, a switch individual to said line and controllable from the subscriber's telephone, a release-circuit for conducting current to restore the said individual switch, provided with a normally closed switch-point, the said switch adapted for connecting the subscriber's line 15 with the repeater, said repeater provided with a relay for controlling said switch-point in the release-circuit, outgoing trunk-lines, an automatic switch for the outer end of each of said outgoing trunk-lines, cords 20 and plugs for use in extending connection from the calling subscriber's line to any one of said outgoing trunk-lines, jacks for said outgoing trunk-lines, and means for releasing said automatic switches, operatively controlled by the withdrawal of the plugs from the jacks. 25
- 30 66. In an automatic and manual telephone trunking and release system, the combination of a calling subscriber's line, a subscriber's telephone, a repeater, an individual-switch for said line, controllable by the subscriber, adapted for connecting the line with the said repeater, a main or central station, a trunk-line connecting the repeater with the said main or central station, a line signal individual to said trunk-line, said repeater provided with a relay adapted to respond to trouble on the line and operate said line signal, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks. 40
- 45 67. In an automatic and manual telephone trunking and release system, the combination of a repeater, a calling subscriber's line, a subscriber's telephone, a line-switch controlled by the subscriber, adapted to connect the subscriber's line with the repeater, a main or central station, a trunk-line connecting the repeater with the said main or central station, a line signal individual to said trunk-line, adapted to be operated when the subscriber's line and repeater are 50 connected, a circuit for conducting current for said line signal, a line-relay for controlling said circuit, an energizing circuit for said line-relay, said repeater provided with a relay for controlling said energizing circuit, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks. 55
- 60 68. In an automatic and manual telephone trunking and release system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to said trunk-line, controllable from the repeater, and means whereby said signal is responsive to trouble on the line, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks. 65
- 70 69. In an automatic and manual telephone trunking and release system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to the trunk-line, controllable from said repeater, responsive to incoming calls, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks. 75
- 75 70. In an automatic and manual telephone trunking and release system, the combination of a repeater, a calling subscriber's line, a subscriber's telephone, a line-switch controllable by the subscriber, adapted for connecting the repeater with the subscriber's line, a main or central station, a trunk-line connecting the repeater with the main or central station, a line signal relay individual to said trunk-line, a cut-off-relay provided with armatures for said trunk-line, a line 80

signal relay energizing circuit including said armatures, said repeater provided with a relay and switch-contacts, means for closing said switch-contacts to energize the repeater relay, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks.

15 71. In an automatic and manual telephone trunking and release system, the combination of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal relay individual to the trunk-line, a cut-off-relay provided with armatures for said trunk-line, an energizing circuit for said line signal relay comprising one of said armatures, said repeater provided with normally open switch-contacts, means for closing said normally open switch-contacts to energize said line signal relay, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks.

40 72. In an automatic and manual telephone trunking and release system, the combination of a repeater, a calling subscriber's line, a subscriber's telephone, a switch individual to the subscriber's line, controllable from the telephone, a release-circuit for conducting current for releasing or restoring said individual-switch, said switch adapted for connecting the subscriber's line with the repeater, said repeater provided with normally closed switch-contacts and normally open switch-contacts included in said circuit, means for closing the said normally open switch-contacts to send current over the release-circuit to restore the individual-switch, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks.

65 73. In an automatic and manual tele-

phone trunking and release system, the combination of a repeater, a calling subscriber's line, a subscriber's telephone, an individual line-switch controllable by the subscriber, a subscriber's device for transmitting an electric impulse for operating said switch, said switch adapted for connecting the subscriber's line with the repeater, a line-switch release-circuit comprising normally closed switch-contacts, and normally open switch-contacts, a main or central station, a trunk-line connecting the repeater with the said main or central station, said repeater provided with a relay, a relay energizing circuit comprising a conductor of said trunk-line, including also normally closed switch-contacts at the repeater, and a suitable return circuit, the said normally open release-circuit switch-contacts being controlled by the said repeater relay, the said relay energizable to cause said release-circuit to release or restore the line-switch, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks.

74. In an automatic and manual telephone trunking and release system, the combination of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relays in series with the subscriber's line-conductors, outgoing trunk-lines, an automatic switch for the outer end of each of said outgoing trunk-lines, cords and plugs for use in extending connection from the calling subscriber's line to any one of said outgoing trunk-lines, jacks for said outgoing trunk-lines, and means for releasing said automatic switches, operatively controlled by the withdrawal of the plugs from the jacks.

75. In an automatic and manual telephone trunking and release system, the combination of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relay-windings in series with the subscriber's telephone, outgoing trunk-lines, an automatic switch for the outer end of each of said outgoing trunk-lines, cords and plugs for use in extending connection from the calling subscriber's line to any one of said outgoing

- trunk-lines, jacks for said outgoing trunk-lines, and means for releasing said automatic switches, operatively controlled by the withdrawal of the plugs from the jacks.
- 5 76. In an automatic and manual telephone trunking and release system, the combination of a repeater, a calling subscriber's line, a subscriber's telephone, a subscriber's switch-hook, a subscriber's induction-coil, 10 an individual line-switch operable by the subscriber, adapted for connecting the subscriber's line with the repeater, said repeater provided with a pair of relays, an energizing circuit for said relays, comprising the relays in series with the switch-hook and a winding of said induction-coil, outgoing trunk-lines, an automatic switch for the outer end of each of said outgoing trunk-lines, cords and plugs for use in extending 15 connection from the calling subscriber's line to any one of said outgoing trunk-lines, jacks for said outgoing trunk-lines, and means for releasing said automatic switches, operatively controlled by the withdrawal 20 of the plugs from the jacks.
77. In an automatic and manual telephone trunking and release system, the combination of a repeater, a calling subscriber's line, a subscriber's telephone, an individual line-switch operable by the subscriber, a main or central station, a trunk-line leading through the repeater to the main or central station, said line-switch adapted to connect the subscriber's line with the trunk-line, 25 said repeater provided with means for dividing the trunk-line into inductively connected sections, a battery having one pole grounded, said repeater provided with a relay normally connected with the non-grounded pole of the battery, the other terminal of the relay being connected with one of the trunk-line-conductors at one side of said inductive means, said repeater having another relay connected with the trunk-line 30 at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to 35 ground and the other terminal thereof connected with the individual-switch, outgoing trunk-lines, an automatic switch for the outer end of each of said outgoing trunk-lines, cords and plugs for use in extending 40 connection from the calling subscriber's line to any one of said outgoing trunk-lines, jacks for said outgoing trunk-lines, and means for releasing said automatic switches, operatively controlled by the withdrawal 45 of the plugs from the jacks.
- 50
- 55
- 60
- 65

78. The combination, in a system for trunking between subscribers of different exchanges or stations, of a repeater, a calling subscriber's line, a subscriber's telephone, a switch individual to said line and controllable from the subscriber's telephone, a release-circuit for conducting current to restore the said individual-switch, provided with a normally closed switch-point, the said switch adapted for connecting the subscriber's line with the repeater, said repeater provided with a relay for controlling said switch-point in the release-circuit, 70 a manual switchboard, outgoing trunk-lines, a trunking switchboard, other subscribers' 75 telephone lines terminating at said manual switchboard, said trunking board provided with multiple-jacks connected with the telephone lines terminating at the manual board, means by which the trunking board 80 operator can connect the said calling subscriber's line with any one of said other telephone lines, and means by which the manual board operator can cause the trunking board operator to connect any one of 85 said other telephone lines with any one of 90 said outgoing trunk-lines.

79. The combination, in a system for trunking between subscribers of different exchanges or stations, of a calling subscriber's line, a subscriber's telephone, a repeater, an individual-switch for said line, controllable by the subscriber, adapted for connecting the line with the said repeater, a main or central station, a trunk-line connecting the 95 repeater with the said main or central station, a line signal individual to said trunk-line, said repeater provided with a relay adapted to respond to trouble on the line and operate said line signal, a manual 100 switchboard, outgoing trunk-lines, a trunking switchboard, other subscribers' telephone lines terminating at said manual switchboard, said trunking board provided with multiple-jacks connected with the telephone lines terminating at the manual board, means by which the trunking board 105 operator can connect the said calling subscriber's line with any one of said other telephone lines, and means by which the manual board operator can cause the trunking board operator to connect any one of 110 said other telephone lines with any one of 115 said outgoing trunk-lines.

80. The combination, in a system for 120 trunking between subscribers of different exchanges or stations, of a repeater, a calling subscriber's line, a subscriber's telephone, a line-switch controlled by the subscriber, adapted to connect the subscriber's 125 line with the repeater, a main or central station, a trunk-line connecting the repeater with the said main or central station, a line signal individual to said trunk-line, adapted to be operated when the subscriber's 130

and repeater are connected, a circuit for conducting current for said line signal, a line-relay for controlling said circuit, an energizing circuit for said line-relay, said 5 repeater provided with a relay for controlling said energizing circuit, a manual switchboard, outgoing trunk-lines, a trunking switchboard, other subscribers' telephone lines terminating at said manual 10 switchboard, said trunking board provided with multiple-jacks connected with the telephone lines terminating at the manual board, means by which the trunking board operator can connect the said calling subscriber's line with any one of said other 15 telephone lines, and means by which the manual board operator can cause the trunking board operator to connect any one of said other telephone lines with any one of 20 said outgoing trunk-lines.

81. The combination, in a system for trunking between subscribers of different exchanges or stations, of a repeater, a calling subscriber's line, a subscriber's telephone, a 25 line-switch controllable by the subscriber, adapted for connecting the subscriber's line with the repeater, a main or central station, a trunk-line connecting the repeater with the said main or central station, a line signal 30 individual to said trunk-line, controllable from the repeater, and means whereby said signal is responsive to trouble on the line, a manual switchboard, outgoing trunk-lines, a trunking switchboard, other subscribers' 35 telephone lines terminating at said manual switchboard, said trunking board provided with multiple-jacks connected with the telephone lines terminating at the manual board, means by which the trunking board operator can connect the said calling subscriber's line 40 with any one of said other telephone lines, and means by which the manual board operator can cause the trunking board operator to connect any one of said other telephone 45 lines with any one of said outgoing trunk-lines.

82. The combination, in a system for trunking between subscribers of different exchanges or stations, of a repeater, a calling subscriber's line, a subscriber's telephone, a 50 line-switch controllable by the subscriber, adapted for connecting the subscriber's line with the repeater, a main or central station, a trunk-line connecting the repeater with 55 the said main or central station, a line signal individual to the trunk-line, controllable from said repeater, responsive to incoming calls, a manual switchboard, outgoing trunk-lines, a trunking switchboard, other subscribers' 60 telephone lines terminating at said manual switchboard, said trunking board provided with multiple-jacks connected with the telephone lines terminating at the manual board, means by which the trunking board operator can connect the said calling subscriber's line 65 with any one of said other telephone lines, and means by which the manual board operator can cause the trunking board operator to connect any one of said other telephone lines with any one of said outgoing trunk-lines.

subscriber's line with any one of said other telephone lines, and means by which the manual board operator can cause the trunking board operator to connect any one of said other telephone lines with any one of 70 said outgoing trunk-lines.

83. The combination, in a system for trunking between subscribers of different exchanges or stations, of a repeater, a calling subscriber's line, a subscriber's telephone, a 75 line-switch controllable by the subscriber, adapted for connecting the repeater with the subscriber's line, a main or central station, a trunk-line connecting the repeater with the main or central station, a line signal relay 80 individual to said trunk-line, a cut-off-relay provided with armatures for said trunk-line, a line signal relay energizing circuit including said armatures, said repeater provided with a relay and switch-contacts, 85 means for closing said switch-contacts to energize the repeater relay, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line 90 with any one of said other telephone lines, and means by which the manual board operator can cause the trunking board operator to connect any one of said other telephone lines with any one of 95 said outgoing trunk-lines.

84. The combination, in a system for trunking between subscribers of different exchanges or stations, of a repeater, a calling subscriber's line, a subscriber's telephone, a line-switch controllable by the subscriber, 100 adapted for connecting the subscriber's line with the repeater, a main or central station, a trunk-line connecting the repeater with the said main or central station, a line signal relay individual to the trunk-line, a cut-off-relay provided with armatures for said 105 trunk-line, an energizing circuit for said line signal relay comprising one of said armatures, said repeater provided with normally open switch-contacts, means for closing said normally open switch-contacts to energize said line signal relay, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line 110 with any one of said other telephone lines, and means by which the manual board operator can cause the trunking board operator to connect any one of said other telephone lines with any one of 115 said outgoing trunk-lines.

85. The combination, in a system for trunking between subscribers of different exchanges or stations, of a repeater, a calling subscriber's line, a subscriber's telephone, a line-switch controllable by the subscriber, adapted for connecting the subscriber's line with the repeater, a main or central station, a trunk-line connecting the repeater with the said main or central station, a line signal individual to the trunk-line, controllable from said repeater, responsive to incoming calls, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line 120 with any one of said other telephone lines, and means by which the manual board operator can cause the trunking board operator to connect any one of said other telephone lines with any one of 125 said outgoing trunk-lines.

85. The combination, in a system for trunking between subscribers of different exchanges or stations, of a repeater, a calling subscriber's line, a subscriber's telephone, a switch individual to the subscriber's line, controllable from the telephone, a release-circuit for conducting current for releasing or restoring said individual-switch, said switch adapted for connecting the subscriber's line with the repeater, said repeater provided with normally closed switch-contacts and normally open switch-contacts included in said circuit, means for closing the said normally open switch-contacts to send current over the release-circuit to restore the individual-switch, a manual switchboard, outgoing trunk-lines, a trunking switchboard, other subscribers' telephone lines terminating at said manual switchboard, said trunking board provided with multiple-jacks connected with the telephone lines terminating at the manual switchboard, means by which the trunking board operator can connect the said calling subscriber's line with any one of said other telephone lines, and means by which the manual board operator can cause the trunking board operator to connect any one of said other telephone lines with any one of said outgoing trunk-lines.

86. The combination, in a system for trunking between subscribers of different exchanges or stations, of a repeater, a calling subscriber's line, a subscriber's telephone, an individual line-switch controllable by the subscriber, a subscriber's device for transmitting an electric impulse for operating said switch, said switch adapted for connecting the subscriber's line with the repeater, a line-switch release-circuit comprising normally closed switch-contacts, and normally open switch-contacts, a main or central station, a trunk-line connecting the repeater with the said main or central station, said repeater provided with a relay, a relay energizing circuit comprising a conductor of said trunk-line, including also normally closed switch-contacts at the repeater, and a suitable return circuit, the said normally open release-circuit switch-contacts being controlled by the said repeater relay, the said relay energizable to cause said release-circuit to release or restore the line-switch, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line with any one of said other telephone lines, and means by which the manual board operator can cause the trunking board operator to connect the trunking board operator to the trunking board.

87. The combination, in a system for trunking between subscribers of different exchanges or stations, of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relays in series with the subscriber's line-conductors, a manual switchboard, outgoing trunk-lines, a trunking switchboard, other subscribers' telephone lines terminating at said manual switchboard, said trunking board provided with multiple-jacks connected with the telephone lines terminating at the manual switchboard, means by which the trunking board operator can connect the said calling subscriber's line with any one of said other telephone lines, and means by which the manual board operator can cause the trunking board operator to connect any one of said other telephone lines with any one of said outgoing trunk-lines.

88. The combination, in a system for trunking between subscribers of different exchanges or stations, of a repeater, a calling subscriber's line, a subscriber's telephone, an individual line-switch operable by the subscriber, adapted for connecting the subscriber's line with the repeater, said repeater provided with a pair of relays, an energizing circuit for said relays, comprising the relay-windings in series with the subscriber's telephone, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line with any one of said other telephone lines, and means by which the manual board operator can cause the trunking board operator to connect any one of said other telephone lines with any one of said outgoing trunk-lines.

89. The combination, in a system for trunking between subscribers of different exchanges or stations, of a repeater, a calling subscriber's line, a subscriber's telephone, a subscriber's switch-hook, a subscriber's induction-coil, an individual line-switch operable by the subscriber, adapted for connecting the subscriber's line with the repeater, said repeater provided with a pair of relays, an energizing circuit for said relays, comprising the relays in series with the switch-hook and a winding of said in-

120
125
130

- duction-coil, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line with any one of said other telephone lines, and means by which the manual board operator can cause the trunking board operator to connect any one of said other telephone lines with any one of said outgoing trunk-lines.
- 15 90. The combination, in a system for trunking between subscribers of different exchanges or stations, of a repeater, a calling subscriber's line, a subscriber's telephone, an individual line-switch operable by the subscriber, a main or central station, a trunk-line leading through the repeater to the main or central station, said line-switch adapted to connect the subscriber's line with the trunk-line, said repeater provided with means for dividing the trunk-line into inductively connected sections, a battery having one pole grounded, said repeater provided with a relay normally connected with the non-grounded pole of the battery, the other terminal of the relay being connected with one of the trunk-line-conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual-switch, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line with any one of said other telephone lines, and means by which the manual board operator can cause the trunking board operator to connect any one of said other telephone lines with any one of said outgoing trunk-lines.
- 20 91. A telephone exchange system comprising subscribers' lines, multiple-jacks for said lines, other subscribers' lines, connectors for establishing connection with said other subscribers' lines, cords and plugs for use in establishing connection between call-
- 15 90. The combination, in a system for trunking between subscribers of different exchanges or stations, of a repeater, a calling subscriber's line, a subscriber's telephone, an individual line-switch operable by the subscriber, a main or central station, a trunk-line leading through the repeater to the main or central station, said line-switch adapted to connect the subscriber's line with the trunk-line, said repeater provided with means for dividing the trunk-line into inductively connected sections, a battery having one pole grounded, said repeater provided with a relay normally connected with the non-grounded pole of the battery, the other terminal of the relay being connected with one of the trunk-line-conductors at one side of said inductive means, said repeater having another relay connected with the trunk-line at the other side of said inductive means, the other terminal of said last-mentioned relay being connected to ground, said repeater provided with a third relay having one terminal connected to the other trunk-line-conductor at one side of the inductive means, the other terminal of said last-mentioned relay being connected to ground, and said repeater being provided with a fourth relay having one terminal connected to ground and the other terminal thereof connected with the individual-switch, a manual switchboard, outgoing trunk-lines, a trunking switchboard, other subscribers' telephone lines terminating at said manual switchboard, said trunking board provided with multiple-jacks connected with the telephone lines terminating at the manual board, means by which the trunking board operator can connect the said calling subscriber's line with any one of said other telephone lines, and means by which the manual board operator can cause the trunking board operator to connect any one of said other telephone lines with any one of said outgoing trunk-lines.
- 25 92. A telephone exchange system comprising a main or central trunking station, sub-central stations, outgoing and incoming trunk-lines connecting the main station with the sub-central stations, subscribers' lines terminating at the sub-central stations, subscriber-operated automatic switches located at the sub-central stations, adapted for connecting any calling subscriber's line with a non-busy incoming trunk-line, manual switchboard apparatus at the main or central station, adapted for use in connecting any selected incoming trunk-line with a non-busy outgoing trunk-line, automatic switching machinery located at the sub-central stations, operatively controlled from the manual switchboard at the main or central station, adapted for completing the establishment of connection with the line of any called subscriber, multiple-jacks on said switchboard, and other subscribers' lines connected with said jacks.
- 30 93. A telephone exchange system comprising subscribers' lines, a manual switchboard provided with visual signals, repeaters and incoming trunk-lines through which calling subscribers operate the said visual signals to attract the attention of the operator, connectors for making connection directly with the line of any called subscriber, outgoing trunk-lines leading to said connectors, operator-controlled means for making connection between incoming and outgoing trunk-lines, and an operator's impulse-transmitter for operating the connectors over the outgoing trunk-lines.
- 35 94. A telephone exchange system comprising a group of subscribers' lines, telephones for said lines, trunk-lines less in number than the said subscribers' lines, selectively-operated switching machinery for said subscribers' lines comprising trunk preselecting equipment, adapted for connecting a calling subscriber's line with a preselected non-busy trunk-line, a trunking switchboard, a subscriber's switchboard, a group of subscribers' telephone lines for said subscriber's switchboard, subscribers' telephones for said second group of subscribers' lines, multiple-jacks for said last-mentioned subscribers' lines, distributed on said subscriber's switchboard and trunking board, cords and plugs for connecting any trunk-line jack with any subscriber's multiple-jack, whereby any one of the telephones of the first group may be connected with any one of the telephones of the second group.

95. A telephone exchange system comprising subscribers' telephone lines, telephones for said lines, trunk-lines less in number than the said subscribers' lines, selectively-operated trunking switches for said lines comprising trunk preselecting equipment, adapted for connecting any calling subscriber's line with a preselected trunk-line, a manual switchboard, trunking jacks on said board, other trunk-lines having multiple-jacks on said board, connectors in which said other trunk-lines terminate, said subscribers' lines provided with multiple-terminals located in said connectors, and cords and plugs located on said switchboard, adapted for connecting a preselected trunk-line with another trunk-line leading to a connector, each of said selectively-operated trunking switches being individual to a subscriber's line.

96. A telephone exchange system comprising a subscriber's telephone, a subscriber's line with normally open conductors, a repeater, and a line-switch adapted to connect said line and repeater, one side of said subscriber's line normally connected to ground, a battery having one pole connected to ground, the other side of the line connected with the non-grounded pole of said battery, a trip-magnet in the non-grounded battery connection, whereby when the subscriber's line is closed the said trip-magnet is energized to operate the line-switch, a non-grounded and a grounded relay in said repeater, a cut-off-relay for the line-switch, circuits controlled by said line-switch when operated, whereby the non-grounded relay of the repeater is energized through the said ground connection, the grounded relay is short-circuited, and the cut-off-relay energized, and circuits controlled by said cut-off-relay, whereby the said short-circuit is removed from across the said grounded relay, the ground connection to said line-conductor is removed, and the circuits so adjusted that the non-grounded relay is energized through the grounded relay, both of said relays then being energized in series, and the trip-magnet deenergized.

97. In a telephone system, a trunk line, a manual switchboard at which said trunk line terminates, reactive connections in the trunk line at the other end thereof, relays connected with the trunk line at opposite sides of said reactive connections, means by which a calling subscriber automatically connects with the said trunk line, means controlled by an operator for extending connection to the line of the called subscriber, a signal at said switchboard, and means for operating said signal when said trunk line is seized.

98. In a telephone system, a trunk line with condensers therein, relays connected with the trunk line at opposite sides of said

condensers, means for automatically connecting a calling subscriber to said trunk line, a spring jack on the side of said condensers opposite from the end seized, and a signal operated as soon as connection is made with said trunk line.

99. In a telephone system, a trunk line, condensers in said trunk line dividing it into two sections, relays connected with the trunk line at opposite sides of said condensers, means for supplying talking current through two of said relays to one section to the calling subscriber's substation, automatic means for connecting the calling subscriber to said section of the trunk line, a signal associated with the other section at the other end of said trunk line, and means for operating said signal from the calling line over said other section.

100. In a telephone system, trunk lines, means for preselecting a trunk line, a subscriber's preliminary trunking switch adapted to operate to connect with a preselected trunk without reference to the called number when the calling subscriber takes down the receiver, manual means for extending connection from said trunk, and centralized means for furnishing current for connecting purposes.

101. In a telephone system, means for establishing a connection between a calling and a called subscriber's line, said means including trunk lines, means for preselecting a trunk line, a preliminary trunking switch, a manual switchboard provided with jacks and plugs and with an apparatus for supervising a connection established with a called line through the medium of said preliminary trunking switch of a calling line and a preselected trunk line, and centralized means for furnishing current for connecting purposes.

102. A telephone exchange system comprising a calling and a called subscriber's line, a subscriber's telephone, means for extending connection to the called subscriber's line including a repeater, an individual switch for said line, controllable by the subscriber, adapted for connecting the line with the said repeater, a main or central station, a trunk-line connecting the repeater with the said main or central station, a line signal individual to said trunk-line, said repeater provided with a relay adapted to respond to trouble on the line and operate said line signal, and means having vertical and then rotary motion for seizing a called line.

103. A telephone exchange system comprising a repeater, a calling and a called subscriber's line, a subscriber's telephone, means for extending connection to the called subscriber's line including a line switch controlled by the subscriber, adapted to connect the subscriber's line with the repeater, a main or central station, a trunk-line con-

necting the repeater with the said main or central station, a line signal individual to said trunk-line, adapted to be operated when the subscriber's line and repeater are connected, a circuit for conducting current for said line signal, a line relay for controlling said circuit, an energizing circuit for said line relay, said repeater provided with a relay for controlling said energizing circuit, and means having vertical and then rotary motion for seizing a called line.

104. A telephone exchange system comprising a repeater, a calling and a called subscriber's line, a subscriber's telephone, means for extending connection to the called subscriber's line including a line switch controllable by the subscriber, adapted for connecting the subscriber's line with the repeater, a main or central station, a trunk-line connecting the repeater with the said main or central station, a line signal individual to said trunk-line, controllable from the repeater, and means whereby said signal is responsive to trouble on the line, and means having vertical and then rotary motion for seizing a called line.

105. A telephone exchange system comprising a repeater, a calling and a called subscriber's line, a subscriber's telephone, means for extending connection to the called subscriber's line including a line switch controllable by the subscriber, adapted for connecting the subscriber's line with the repeater, a main or central station, a trunk-line connecting the repeater with the said main or central station, a line signal individual to the trunk-line, controllable from said repeater, responsive to incoming calls, and means having vertical and then rotary motion for seizing a called line.

106. A telephone exchange system comprising a repeater, a calling and a called subscriber's line, a subscriber's telephone, means for extending connection to the called subscriber's line including a line switch controllable by the subscriber, adapted for connecting the repeater with the subscriber's line, a main or central station, a trunk-line connecting the repeater with the main or central station, a line signal relay individual to said trunk-line, a cut-off relay provided with armatures for said trunk-line, a line signal relay energizing circuit including said armatures, said repeater provided with a relay and switch contacts, means for closing said switch contacts to energize said last-mentioned relay, and means having vertical and then rotary motion for seizing a called line, as set forth.

107. A telephone exchange system comprising a repeater, a calling and a called subscriber's line, a subscriber's telephone, means for extending connection to the called subscriber's line including a line switch controllable by the subscriber, adapted for con-

necting the subscriber's line with the repeater, a main or central station, a trunk-line connecting the repeater with the said main or central station, a line signal relay individual to the trunk-line, a cut-off relay provided with armatures for said trunk-line, an energizing circuit for said line signal relay comprising one of said armatures, said repeater provided with normally open switch contacts, means for closing said normally open switch contacts to energize said line signal relay, and means having vertical and then rotary motion for seizing a called line.

108. A telephone exchange system comprising a repeater, a calling and a called subscriber's line, a subscriber's telephone, means for extending connection to the called subscriber's line including a switch individual to the subscriber's line, controllable from the telephone, a release circuit for conducting current for releasing or restoring said individual switch, said switch adapted for connecting the subscriber's line with the repeater, said repeater provided with normally closed switch contacts and normally open switch contacts included in said circuit, means for closing the said normally open switch contacts to send current over the release circuit to restore the individual switch, means for opening the normally closed contacts to prevent a release during talking, and means having vertical and then rotary motion for seizing a called line.

109. A telephone exchange system comprising a repeater, a calling and a called subscriber's line, a subscriber's telephone, means for extending connection to the called subscriber's line including an individual line switch controllable by the subscriber, a subscriber's device for transmitting an electric impulse for operating said switch, said switch adapted for connecting the subscriber's line with the repeater, a line switch release circuit comprising normally closed switch contacts, and normally open switch contacts, a main or central station, a trunk-line connecting the repeater with the said main or central station, means having vertical and then rotary motion for seizing a called line, said repeater provided with a relay, a relay energizing circuit comprising a conductor of said trunk-line, including also normally closed switch contacts at the repeater, and a suitable return circuit, the said normally open release circuit switch contacts being controlled by the said repeater relay, the said relay energizable to cause said release circuit to release or restore the line switch.

110. A telephone exchange system comprising a repeater, a calling and a called subscriber's line, a subscriber's telephone, means for extending connection to the called subscriber's line including an individual line

switch operable by the subscriber, adapted for connecting the subscriber's line with the repeater, means having vertical and then rotary motion for seizing a called line, said repeater provided with relays, and an energizing circuit for said relays, comprising the line conductors in series.

111. A telephone exchange system comprising a repeater, a calling and a called subscriber's line, a subscriber's telephone, means for extending connection to the called subscriber's line including an individual line switch operable by the subscriber, adapted for connecting the subscriber's line with the repeater, means having vertical and then rotary motion for seizing a called line, said repeater provided with relays, and an energizing circuit for said relays, comprising the relay windings in series with the subscriber's transmitter.

112. A telephone exchange system comprising a repeater, a calling and a called subscriber's line, a subscriber's telephone, means for extending connection to the called subscriber's line including a subscriber's switch-hook, a subscriber's induction coil, an individual line switch operable by the subscriber, adapted for connecting the subscriber's line with the repeater, means having vertical and then rotary motion for seizing a called line, said repeater provided with relays, and an energizing circuit for said relays, comprising the relays in series with the switch-hook and a winding of said induction coil.

113. A telephone exchange system comprising a repeater, a calling and a called subscriber's line, a subscriber's telephone, means for extending connection to the called subscriber's line including an individual line switch operable by the subscriber, a main or central station, a trunk-line leading through the repeater to the main or central station, means having vertical and then rotary motion for seizing a called line, said line switch adapted to connect the subscriber's line with the trunk-line, said repeater provided with means for dividing the trunk-line into inductively-connected sections, a battery having one pole grounded, said repeater provided with a relay normally connected with the non-grounded pole of the battery, the other terminal of the relay being connected with one of the trunk-line conductors at one side of said inductive means, said repeater having another relay connected with the trunk-line at the other side of said inductive means, the other terminal of said last-mentioned relay being connected to ground, said repeater provided with a third relay having one terminal connected to the other trunk-line conductor at one side of the inductive means, the other terminal of said last-mentioned relay being connected to ground, and said repeater being provided with a fourth

relay having one terminal connected to ground and the other terminal thereof connected with the individual switch.

114. A telephone exchange system comprising subscribers' lines, multiple jacks for said lines, other subscribers' lines, connectors having vertical and then rotary motion for establishing connection with said other subscribers' lines, cords and plugs for use in establishing connection between calling and called lines, an operator's ringing apparatus for use when connection is made with a called line by simply plugging into a multiple jack, and automatic ringing apparatus allotted to said connectors, adapted to automatically ring or signal any called subscriber when a connector is used for making connection with the called line.

115. A telephone exchange system comprising subscribers' lines, a manual switch-board provided with visual signals, repeaters and incoming trunk-lines through which calling subscribers operate the said visual signals to attract the attention of the operator, connectors having vertical and rotary motion for making connection directly with the line of any called subscriber, outgoing trunk-lines leading to said connectors, operator-controlled means for making connection between incoming and outgoing trunk-lines, and an operator's impulse-transmitter for operating the connectors over the outgoing trunk-lines.

116. A telephone exchange system comprising subscribers' telephone lines, telephones for said lines, trunk-lines less in number than the said subscribers' lines, trunking switches for said lines comprising trunk selecting equipment, adapted for connecting any calling subscriber's line with a preselected trunk-line, a manual switch-board, trunking jacks on said board, other trunk-lines having multiple jacks on said board, connectors in which said other trunk-lines terminate, said subscribers' lines provided with multiple terminals located in said connectors, and cords and plugs located on said switchboard, adapted for connecting a preselected trunk-line with another trunk-line leading to a connector, said connectors having vertical and rotary motion to seize a called line, each of said trunking switches being individual to a subscriber's line.

117. In a telephone system, a trunk-line, a manual switchboard at which said trunk-line terminates, reactive connections in the trunk-line at the other end thereof, relays connected with the trunk-line at opposite sides of said reactive connections, means by which a calling subscriber automatically connects with the said trunk-line, and means having up-and-around motion controlled by an operator for extending connection to the line of the called subscriber.

118. In a telephone system, a trunk-line, means by which a calling subscriber automatically connects his line with the said trunk-line, to extend connection to an operator's position, means having up-and-around motion controlled by an operator for extending connection from the trunk-line to the line of the called subscriber, and automatic means for signaling the called subscriber.

119. A telephone system comprising subscribers' telephone lines extending from substations to an exchange, call signals controlled from the substations of said lines, operators' answering means adapted for connection with said lines, other telephone lines, multiple terminals for said other lines, switches common to said answering means for directly connecting with said other lines, operators' switching means to enable the operators to transmit directive currents to said switches to cause them to connect said answering means with terminals of particular ones of said other telephone lines, whereby connections between subscribers are completed, means individual to each switch for automatically signaling the called subscriber, and a central source of current and branches to supply current therefrom to calling and called substations for conversation.

120. A telephone exchange system including telephone lines, answering terminals at the exchange, signals at the exchange adapted to be controlled by currents over said lines, operators' connective means adapted to be connected with said answering terminals, multiple terminals of said lines at the exchange, switches common to said operators' connecting means adapted for operation to complete connections from said answering terminals to said multiple terminals, operators' switching means for controlling the operation of said switches to select terminals of particular lines, means individual to each switch for automatically signaling the called subscriber, means for changing the electrical character of its terminals to render them busy when connection is made with a line, automatic test means for said switches sensitive to the electrical character of said terminals to render connections ineffective when said terminals are busy, a central source of current and branches to energize calling and called subscribers' transmitters therefrom for conversation, and means for releasing said switches when disconnection is required.

121. A multiple switchboard telephone exchange system including telephone lines, signals controllable over said lines at the exchange, answering jacks, operators' cord circuits provided with plugs for connecting with said jacks, multiple calling terminals of said lines divided into groups, a plural-

ity of connector switches common to said operators' cord circuits for directly connecting with the lines of each of said groups, means controlled by the operators for completing connections from said cord circuits to said connector switches, calling devices controlled by the operators for transmitting directive switching currents to said switches to cause them to select particular called lines of their groups, means for changing the electrical character of its terminals to render them busy when connection is made with a line, test means for said switches whereby a connection made with a busy line is ineffective, means individual to each switch for automatically signaling the called subscriber, and a central source of current and apparatus for supplying current therefrom to calling and called subscribers' lines for conversation.

122. A multiple switchboard telephone exchange system including telephone lines, signals controllable over said lines at the exchange, answering spring jacks, operators' cord circuits provided with plugs for connecting with said jacks, multiple calling terminals of said lines divided into groups, a plurality of connector switches common to said cord circuits for directly connecting with the lines of each of said groups, manually manipulated operators' switches for connecting said cord circuits with said switches, calling devices controlled by the operators for transmitting directive switching currents to said switches to cause them to select particular called lines of their groups, means for changing the electrical character of its terminals to render them busy when connection is made with a line, test means for said switches whereby a connection made with a busy line is ineffective, means individual to each switch for automatically signaling the called subscriber, and a central source of current and apparatus for supplying current therefrom to calling and called subscribers' lines for conversation.

123. A multiple switchboard telephone exchange system including subscribers' lines, call signals adapted for operation under substation control, answering spring jacks, multiple calling terminals of said lines divided into groups, a plurality of connector switches for directly connecting with the lines of each of said groups, circuits extending to said switches for controlling their operation, spring jack terminals of said circuits common to said connector switch, operators' cord circuits having answering plugs for connecting with said answering spring jacks and calling plugs for connecting with said spring jack terminals, calling devices controlled by the operators for transmitting directive switching currents to said switches to cause them to select particular lines of

- their groups, automatic test means for said connector switches to cause them to avoid busy lines, means individual to each switch for automatically signaling the called subscriber, and a central source of current and branches therefrom to supply current to calling and called substations for conversation.
124. In a telephone system, a calling telephone line, an operator's connecting means including plugs and jacks, means controlled over the telephone for automatically selecting a trunk for extending connection to said connecting means, and means including an automatic selecting switch controlled by the operator for completing the connection to the called telephone line said switch being provided with common battery means for supplying talking current.
125. In a telephone system, a plurality of answering jacks located on a manual switchboard, a mechanism for automatically selecting idle jacks, a master switch for controlling said mechanism, and means by which a calling subscriber controls said mechanism over a metallic line circuit.
126. In a telephone system, a plurality of answering jacks located on a manual switchboard, a repeater for each jack, a mechanism having movable switch wipers for automatically selecting idle repeaters to obtain connection with an idle jack, and means by which the calling subscriber controls said mechanism over the two sides of the calling line in series.
127. In a telephone system, a manual switchboard, a plurality of trunks leading to said switchboard, a progressively movable switch individual to the calling line for automatically selecting idle trunks, controlled by the calling subscriber over the two sides of the calling line in series, a master switch for controlling the selecting movement of said individual switch, means at said board for answering the call, and electromagnetically-operated selecting means controlled by the operator for then extending the call to the called line, said switch being provided with common battery means for supplying talking current.
128. In a telephone system, a manual switchboard, a plurality of trunks leading to said switchboard, a progressively movable switch individual to the calling line for automatically selecting idle trunks, controlled by the calling subscriber over the two sides of the calling line in series, a master switch for controlling the selecting movement of said individual switch, means at said board for answering the call, and means for completing the call to the called line including an electromagnetically-operated selecting switch controlled by the operator at said board, said switch being provided with com-
- mon battery means for supplying talking current.
129. In a telephone system, a plurality of subscribers' lines, means including a progressively movable switch individual to a calling line and an operator's cord circuit for establishing a connection between two of said lines, means operated solely by the completion of the connection for automatically signaling the called subscriber, and means controlled by one of said subscribers for releasing part of said connection, independent of any operation on the part of the manual operator, whereby said subscriber can then make a second call.
130. In a telephone system, a pair of subscribers' lines, means including an automatic switch individual to the calling line and a manual operator's cord circuit for establishing a connection between said lines, means operated solely by the completion of the connection for automatically signaling the called subscriber, and means controlled by a subscriber for releasing said automatic switch.
131. In a telephone system, a subscriber's line, a manual operator's cord circuit, means including an automatic switch individual to said line for extending a connection from said line to said cord circuit, means operated solely by the completion of the connection for automatically signaling the called subscriber, and means controlled by said subscriber for releasing said switch, independent of any operation on the part of the operator.
132. In a telephone system, a subscriber's line, an operator's cord circuit, means including a non-numerical switch individual to said line for extending a connection from said line to said cord circuit, means operated solely by the completion of the connection for automatically signaling the called subscriber, and means controlled by said subscriber for releasing said switch independent of any operation on the part of the operator.
133. A telephone exchange system comprising a subscriber's line normally open at the substation thereof, a subscriber's telephone, a battery having one pole grounded, and an individual selectively-operated trunking switch for said subscriber's line, together with trunk-lines leading from said switch, said subscriber's line having one side connected with one terminal of the battery, the other side of the subscriber's line being connected with the other pole of said battery, a circuit closing member for said switch, said switch provided with a magnet, the armature of which moves said member to close connection between the line and any one of said trunk lines when the subscriber closes a line circuit at the substation, said magnet having a winding included in the connection

between the battery and the said other side of the subscriber's line, and a cut-off-relay for disconnecting the battery from the line.

134. In a telephone system, a calling line, 5 a called line, means for connecting the two comprising a progressively movable switch individual to the calling line and manual trunking equipment, progressively movable automatic trunking equipment, and means 10 operated solely by the completion of the connection for automatically signaling the called subscriber after the called line is found.

135. In a telephone system, a plurality of 15 subscribers' lines, a plurality of trunk lines common to said subscribers, an operator's board, terminals in said board for said trunk lines, automatic trunking means for connecting a subscriber's line with one of 20 the trunk lines and for making the trunk line busy, and means responsive to the establishment of the connection between the line and the trunk for preselecting the next idle trunk to be used for the next call.

25 136. In a telephone system, a plurality of lines, a plurality of trunks common to said lines, a manual board, said trunks terminating in said board, a signal for each trunk, automatic means for connecting any 30 line with any trunk and for operating the trunk signal at the board, a busy test circuit for said trunk, means for establishing a guarding potential in said circuit for making the trunk busy, and means responsive to said potential for preselecting the 35 next idle trunk to be used.

137. In a telephone system, a plurality of 40 lines, a plurality of trunks, an operator's board, terminals for said trunks in said board and a signal for each trunk, an automatic trunking switch for each line for connecting the corresponding line with any one of the trunks, a master switch for automatically selecting an idle trunk and for ass- 45 signing the same to the line for the next call, means for operating one of said switches over its line to connect the line with the trunk and to operate the corresponding signal at

the board, a busy test circuit for said trunk, means for applying a guarding potential to 50 said circuit when connection is extended from the line to the trunk, said master switch responsive to said guarding potential for selecting the next idle trunk to be used for the next call. 55

138. In a telephone system, a progressively movable switch, a trunk line individual thereto, a bridge across one end of said trunk line, said bridge grounded at the center and provided with both normally 60 open and normally closed switch points at each side thereof, a relay for controlling the two normally closed switch points, and another relay for controlling the two normally open switch points, said relays for 65 controlling said switch.

139. A telephone exchange system comprising a repeater, a calling subscriber's telephone line including a pair of talking conductors, a subscriber's substation apparatus, a switch individual to said subscriber's line and operable by the subscriber for connecting said subscriber's line with said repeater, a pair of relay windings for 70 said repeater, an energizing circuit for said relay windings, said circuit including said relay windings and said talking conductors all in series. 75

140. A telephone exchange system comprising a repeater, a calling subscriber's line, 80 a subscriber's telephone, a subscriber's switch hook, a subscriber's induction coil, a line switch individual to said telephone line and operable by the subscriber for connecting said line with said repeater, a pair of relay windings for 85 said repeater, an energizing circuit for said relay windings, said circuit including said relay windings, said switch hook, and a winding of said induction coil all in series. 90

Signed by me at Chicago, Cook county, Illinois, this 8th day of May, 1906.

TALBOT G. MARTIN.
